UNITED STATES PATENT OFFICE

JOHN WICKS, OF OAK PARK, ILLINOIS, ASSIGNOR TO RESERVE HOLDING COMPANY, OF KANSAS CITY, MISSOURI, A CORPORATION OF DELAWARE

TELEPHONE SYSTEM

Application filed August 6, 1928. Serial No. 297,611.

The present invention relates to telephone systems in general, but as regards a number of its objects and features, it is concerned more particularly with automatic telephone systems of the so-called inverted type in which talking battery and holding potentials are supplied from a first selector rather than a connector. This case may be considered as an improvement on my co-pending application, Serial No. 714,240, filed May 19, 1924, and Patent No. 1,723,224, granted Aug. 6, 1929.

One of the objects of the invention is to provide a new and improved toll service trunking system to operate in conjunction with the present inverted system and to enable a toll operator to cut in on local connections in case either one of the local subscribers is desired in a toll connection and break down such local connection in order to complete the desired toll connection. In case the desired local subscriber is engaged in a toll connection, the toll operator will be automatically notified of this fact by means of a toll busy tone and she will be unable to cut in and break down such a toll connection.

Another object of the invention is to provide improved metering and zone metering circuit arrangements for metering the call after the termination of conversation. Metering on calls is to take place after the termination of conversation instead of when the called party answers because the completed connection is liable at any time to be interrupted by a toll operator coming in on the connection to establish a desired toll connection.

Another object of the invention is to provide new and improved selectors and selector repeater circuits such that the selectors hunt for a battery potential on their associated test contacts instead of for an absence of ground potential. Selectors of this type are commonly known as "battery hunting" selectors. That is, such selectors, in hunting for an idle trunk, must find battery potential on their associated test contacts in order to switch through, while a ground potential or an absence of potential on such test contacts would cause such selector to rotate.

According to another feature, a new and improved rotary connector accessible for use in both local and toll connections has been provided to take care of the situation in which a calling subscriber may call a common call number and connect with the first idle one of several lines having such a common call number. Circuit arrangements are also provided in this improved connector whereby a calling subscriber can call and connect with a particular one of these subscribers having a common call number.

There are, of course, a number of objects and features subsidiary to the foregoing which may be understood best from a further perusal of this specification.

Referring now to the accompanying drawings comprising Figs. 1 to 7, inclusive, Figs. 1 to 6 show by means of the usual circuit diagrams a sufficient amount of equipment employed in a telephone system embodying the principles of the invention to enable the invention to be understood. Fig. 7 is a diagram showing how the sheets of drawings, on which Figs. 1 to 6 appear, should be arranged in order to be understood best.

Fig. 1 shows a two conductor toll service trunk extending from the jack J at the toll board to the toll transmission selector repeater located at the local automatic exchange. Fig. 1 also shows the cord circuit CC which is one of the cord circuits used by the toll operator to complete connections to the toll service trunk through the jacks such as J. Other trunk lines, such as the trunk line comprising conductors 9 and 10 (extend from the toll board to other automatic offices in this telephone system.

Fig. 2 shows the transmission selector repeater on the incoming end of the interoffice trunk line comprising conductors 9 and 10 extending from jack J, Fig. 1. This transmission selector repeater is of a special design so as to give the operator the correct supervision and so as to enable the operator to control the starting of the application of ringing current to the called line. This selector repeater is also designed so as to enable the operator to cut in on a local established connection and break down such con-

nection in order to complete a toll connection to the desired called subscriber. A transmission selector repeater of the same design is provided in each automatic office and calls thereto are completed from the toll board.

5 The transmission selector repeaters have access to intermediate selectors such as the selectors shown in Fig. 4.

Fig. 3 shows the first selector repeater 10 which is accessible to the line switch LS associated with the line of substation A. This selector repeater is provided with the necessary arrangements for feeding talking battery to the calling subscriber in all cases and 15 to the called subscriber on local calls. It is also provided with the necessary arrangements for preventing the operation of the subscriber's meter when the operator breaks down a local established connection. Circuit 20 arrangements are also provided in the first selector repeater for holding the line switch operated after the calling subscriber has replaced his receiver in order to meter the call upon release. The circuits are also arranged 25 so that the calling subscriber, in making a new call, will not interfere with the metering operation until the metering operation has been completed.

Fig. 4 shows two intermediate selectors, the 30 first of which is shown in detail and is accessible to the first selector repeater shown in Fig. 3. The second intermediate selector which is similar in all respects to the first intermediate selector is accessible from the first 35 intermediate selector and the transmission selector repeater, Fig. 2, located in the local automatic exchange.

Figure 5 shows a rotary connector which 40 is accessible to the second intermediate selector shown in Fig. 4 and is used for calling individual lines and also for calling lines associated in groups with the number of the first line assigned as the call number of the entire group. This rotary connector is also 45 provided with circuit arrangements such that a subscriber may call a particular line out of a group of lines having the same directory call number. This connector is provided with circuit arrangements so as to provide a guarding 50 potential of one character in case a local connection has been established or if the connector has been used to complete a toll connection to provide a discriminating guarding potential on the test contact of the called 55 line. This connector is also provided with means for cutting in on a local connection and breaking down such local connection.

The rotary connector has access to subscribers' lines such as A' and A. The line 60 switch LS' is similar to the line switch LS in Fig. 3 and is individual to the line of subscriber A'.

Fig. 5A shows in detail the manner in 65 which the test contacts accessible to test wiper 464 of the rotary connector are ar-

ranged in order to permit the rotary connector to seize an idle line in a group of lines in case the group number is called, and to connect with any intermediate line of a group, such as illustrated by contacts 482, in 70 case the corresponding number of such intermediate line is called. As illustrated in Fig. 5A, 480 is the test contact accessible to wiper 464 of the first line of a group of lines, while test contacts 482 are intermediate lines and test contact 483 is the test contact of the last line in that particular group. Contact 485 is another first test contact in another group while contact 486 is the last test contact of such other group. Each first contact in the 80 group has battery potential permanently connected thereto by way of the resistances such as 481 and 481' while the last test contacts in the group have ground permanently connected thereto. The test contacts of individual lines, such as 484, and intermediate lines of a group, such as 482, are left dead.

To the left of the dotted line in Fig. 6 there is shown the trunk meter relays associated with the trunk comprising conductors 601 and 602 extending from the local automatic exchange to the distant automatic exchange. The trunk meter relays are individual to the trunk and are taken into use when the first selector repeater is operated to seize the trunk line extending to the distant automatic exchange. The function of the trunk meter relays are to maintain the first selector repeater, Fig. 3, in operated position, until the proper number of metering impulses have 90 been sent for operating the calling subscriber's meter. To the right of the dotted line in Fig. 6 there is shown an incoming selector repeater located in the distant automatic exchange. The incoming selector repeater is accessible to first selector repeaters in the local automatic exchange by way of the trunk line comprising conductors 601 and 602. The incoming selector repeater is provided with means for repeating impulses to 100 succeeding switches in the distant automatic exchange and for providing a holding circuit for the same; for operating an answering bridge in the first selector repeater when the call is answered; for breaking down a local 110 connection in case an operator desires to complete a toll connection to the called subscriber; for preventing the operation of the calling subscriber's meter when the connection has been broken down; and for supplying talking battery to the called subscriber. The incoming selector repeater has access to 120 intermediate selectors such as is shown in Fig. 4 and such intermediate selectors have access to connector switches such as shown in Fig. 5, all of which are located in the distant automatic exchange. The connectors have access to the subscriber's lines terminating in the distant automatic exchange.

Regarding the mechanical construction 130

of the apparatus shown, the various selectors, selector repeaters and connectors are mechanically of the well known vertical and rotary type of switch in which the bank contacts are arranged in horizontal rows or levels.

The various selector repeaters and intermediate selectors are of the type commonly referred to as the "battery hunting" type.

The various line switches, such as LS and LS', are mechanically of the well known rotary type of switch in which the wipers are advanced in one direction only and are advanced upon the back stroke of their associated stepping magnets.

The invention having been described generally, a detailed description of the operation of the apparatus shown will now be given. For this purpose, it will be assumed that the subscriber at substation A, desiring to converse with the subscriber at substation A', removes his receiver and dials the digits in the telephone number of the subscriber at the substation A'.

25 *Calls from substation A to substation A'*

When the receiver is removed at substation A, a circuit is closed over line conductors 201 and 202 for line relay 204 of the line switch LS. Line relay 204 energizes over the calling line and places ground on the associated private normal conductor 218 leading to the banks of the connector switches having access to the line of substation A thereby making this line busy to those connectors, and also closes a circuit through the combined switching and cut-off relay 203 and the motor magnet 205. Line relay 204 also at armature 220 connects test wiper 211 through armature 207 and its resting contact to the junction of relay 203 and magnet 205. Accordingly, if the trunk upon which the wipers of the switch are standing is busy the ground potential encountered by test wiper 211 shunts the relay 203 and prevents it from energizing and affords a direct circuit for the self-interrupting stepping magnet 205. Accordingly, stepping magnet 205 operates in a buzzer-like manner to advance the wipers 210 to 213, inclusive, in search of an idle trunk line.

When an idle trunk line is reached, stepping magnet 205 ceases to operate, and relay 203, being no longer short circuited, energizes in series with stepping magnet 205, which however, does not operate at this time on account of the relatively high resistance of relay 203. Upon energizing, relay 203 disconnects test wiper 211 from the junction of its own winding and that of magnet 205 and connects it to the grounded private normal conductor 218, thereby extending ground through the release trunk conductor 215 of the seized trunk; connects up the meter operating wiper 212 at armature 208; and at armatures 206 and 209 disconnects conductors 201 and 202

from line relay 204 and ground and extends them by way of wipers 210 and 213, conductors 214 and 217, armatures 273 and 279 and their resting contacts, and through the upper and lower windings of line relay 221 and relay 224 to battery and ground. Line relay 221 energizes over the above traced circuit but relay 224 being differential and stiffly adjusted will operate only when ground is connected to both its windings. Line relay 221, upon energizing, at armature 240 closes a circuit for energizing relays 223 and 227 in series; and at armature 241 removes the short circuit from around release relay 222 and closes an energizing circuit for release relay 222 in series with the vertical magnet 230 and the upper and lower windings of relay 226. Release relay 222 energizes over the above traced circuit but relay 226 and vertical magnet 230 do not operate because of the high resistance of release relay 222. Release relay 222, upon energizing, at armature 242 closes a shunt around the armature 261; at armature 244 prepares a point in the holding circuit of relay 223; at armature 244 opens a point in the circuit to the release magnet 232; at armature 245 grounds the release trunk 215 thereby maintaining the line switch LS in operated position when ground is removed from armature 219 by the deenergization of line relay 204; at armature 246 grounds conductor 233; and at armature 247 completes a locking circuit for itself as well as preparing the impulsing circuit through the vertical magnet. The circuit for energizing relays 223 and 227 may be traced as follows: from ground by way of the upper winding of relay 227, normally closed springs controlled by armature 280, normally closed springs controlled by armature 273, armature 240 and its working contact, upper winding of relay 223 and upper winding of relay 224 to battery. Due to its spring adjustments relay 224 is not energized over this circuit. Relay 223, upon energizing, at armature 249 opens a point in the circuit of the release magnet as well as opening a point in the circuit for operating the calling subscriber's meter and at armature 250 prepares an energizing circuit for relay 225 which, however, is opened at armature 270 at this time. Relay 227, upon energizing, at armature 266 connects up ground through resistance 267 in order to maintain relay 223 energized during impulsing; at armature 268 and its working contact connects the dial tone to conductor 214; at armature 269 removes the shunt circuit from around the upper winding of relay 228; at armature 270 and its resting contact opens a point in the circuit of relay 225 and at its working contact completes a locking circuit for itself, extending from ground by way of armature 250; and at armature 271 prepares a circuit for grounding wiper 292 while the first selector repeater is repeating impulses 123

to the succeeding switches in order to improve the impulsing circuit.

Dial tone extends by way of conductor 272, normally closed off-normal springs 265, working contact of armature 268 and said armature, condenser 274, resting contact of armature 273 and said armature; conductor 214, wiper 210, working contact of armature 206 and said armature, conductor 201, over the calling loop, through conductor 202, armature 209 and its working contact, wiper 213, conductor 217, armature 279 and its resting contact, lower winding of line relay 221, and lower winding of differential relay 224 to ground. Upon receipt of the well known dial tone, subscriber A will dial the first digit of the called number.

Responsive to the operation of the calling device, the loop circuit extending through line relay 221 is interrupted a plurality of times, and said line relay falls back a corresponding number of times. Each time line relay 221 falls back, a circuit may be traced by way of the working contact of armature 247, normally closed springs controlled by armature 241, armature 283 and its resting contact, and through the winding of vertical magnet 230 to battery. By the operation of the vertical magnet 230 the switch wipers 290 to 292, inclusive, are operated opposite the desired level of bank contacts. A branch of this impulsing circuit extends through the lower and upper windings of relay 226 to battery, causing such relay to energize. Relay 221 at armature 241, in addition to closing the impulsing circuit, also closes a short circuit around release relay 222 in order to render the release relay slow to release so that it will be maintained in operated position during the impulsing period. At armature 240 line relay 221 closes a circuit extending by way of ground through resistance 267, working contact of armature 266, armature 257, armature 243, make-before-break springs controlled by armature 240, upper winding of relay 223, and upper winding of relay 224 to battery for maintaining relay 223 energized the impulsing period.

Relay 226, upon energizing, at armature 261 opens the initial energizing circuit for line relay 221; at armature 262 opens up a point in the circuit for the rotary magnet 231 so that the rotary magnet will not operate when the off-normal springs 252 operate and close on the first vertical step of the switch; at armature 263 opens a point in the circuit for relay 225; and at armature 264 connects up ground in order to improve the impulsing circuit to the succeeding switches. Relay 226 is slightly slow to fall back when its circuit is open during the impulsing period because of the current flow through relay 222. However, after impulsing, relay 226 falls back after a certain period of time. At armature 262 relay 226 closes a circuit for operating the

rotary magnet 231 as follows: from ground on release trunk conductor 215, armature 255, armature 278, armature 262 and its resting contact, armature 251, off-normal springs 252, resting contact of armature 281 and said armature, interrupter springs 288 of rotary magnet, and winding of rotary magnet 231 to battery. By the operation of the rotary magnet 231, the switch wipers 290 to 292, inclusive, are rotated into engagement with the first set of bank contacts in the selected level. Near the end of its stroke, rotary magnet 231 operates its interrupter springs 288, thereby interrupting its own circuit and the operation of the rotary magnet continues in a buzzer-like manner to step the wipers over the bank contacts in the selected level until the test wiper 291 encounters a battery potential on one of the test contacts.

Assuming that the first idle trunk comprises the conductors 301 to 303, inclusive, extending to the intermediate selector shown in Fig. 4, then when wiper 291 encounters test contact 298 a circuit may be traced for energizing switching relay 229 as follows: ground by way of grounded conductor 233, armature 269 and its working contact, upper winding of switching relay 229, wiper 291, test contact 298, conductor 302, armature 310, normally closed springs controlled by armature 316, normally closed off-normal springs 312, and through resistance 345 to battery. From the foregoing, it will be seen that the rotary magnet rotates the switch wipers until the test wiper 291 engages a test contact having battery potential thereon and therefore the first selector repeater will not stop on grounded test contacts or contacts upon which there are no potentials whatever. Relay 229, upon energizing, at armatures 280 and 284 closes a circuit for energizing line relay 304 of the intermediate selector; at armature 281 opens the rotary magnet circuit so as to stop the rotation of the switch and closes a locking circuit for itself extending by way of grounded release trunk conductor 215 through its lower winding and winding of the rotary magnet in series to battery; at armature 282 prepares a circuit for short circuiting the upper winding of switching relay 229 and connects ground potential extending by way of grounded conductor 233 through the upper low resistance winding of relay 228 to conductor 302; and at armature 283 opens the vertical magnet circuit and short circuits the lower winding of relay 226 as well as closing a circuit for maintaining release relay 222 energized through the upper winding of relay 226. The rotary magnet 231 is not energized in series with the lower winding of switching relay 229 on account of the high resistance of such lower winding. Relay 228, being marginally adjusted, is not energized in series with resistance 345. The circuit for energizing line relay 304 of the in-

termediate selector may be traced as follows: ground by way of lower winding of relay 224, lower winding of relay 223, normally closed springs controlled by armature 279, armature 284, wiper 292, contact 299, conductor 303, normally closed springs controlled by armature 323, winding of line relay 304, normally closed springs controlled by armature 319, conductor 301, bank contact 297, wiper 290, armature 280 and its working contact, normally closed strings controlled by armature 273, armature 240 and its working contact, upper winding of relay 223, and upper winding of relay 224 to battery. Line relay 304 energizes over the above-traced circuit and relay 223 is maintained in operated position when its initial energizing circuit is opened at armature 280.

20 Line relay 304, upon energizing, at armature 310 opens the short circuit around the winding of relay 305, thereby permitting relay 305 to energize, and at armature 311 prepares the impulsing circuit for the vertical magnet. The circuit for energizing relay 305 may be traced as follows: from grounded conductor 302, by way of normally closed eleventh rotary step contacts 317, armature 320 and its resting contact, winding of relay 305, normally closed off-normal spring 312 and through resistance 345 to battery. Relay 305 immediately energizes and at armature 314 opens the circuit to the rotary magnet; at armature 315 prepares the impulsing circuit to the vertical magnet and opens a point in the circuit to the release magnet 309; and at armature 316 prepares a new holding circuit for itself by shunting the normally closed off-normal springs 312 which will open on the first vertical step of the switch.

25 The calling subscriber may now dial the second digit in the called number and responsive thereto line relay 221 in the first selector repeater operates in the same manner as previously described. Each time line relay 221 deenergizes, said relay at armature 240 opens the impulsing circuit extending to the line relay 304 in the intermediate selector.

30 In addition, at armature 241 line relay 221 again completes the circuit for relay 226 so that the latter relay will energize and connect ground by way of armature 264 to conductor 303 so as to improve the impulsing circuit.

35 In the intermediate selector, line relay 304 responds to the interruptions in its circuit and at each deenergization operates the vertical magnet 307. By the operation of the vertical magnet 307, the switch wipers 326 to 328 are operated opposite the desired level of bank contacts. The circuit for energizing the vertical magnet may be traced as follows: ground by way of armature 322, normally closed springs controlled by armature

311, armature 315 and its working contact, and winding of vertical magnet 307 to battery. On the first vertical operation of the switch the normally open off-normal springs 312 close and prepare a circuit for shunting relay 305. During impulsing, however, relay 305 is intermittently energized and shunted by line relay 304 and therefore relay 305 is maintained in energized position during the impulsing period. Shortly after the transmission of impulses, relay 305 is shunted for a sufficient time or time enough to permit such relay to be deenergized. The short circuit of relay 305 may be traced as follows: grounded conductor 302, normally closed springs 317, armature 320 and its resting contact, winding of relay 305, working contact of armature 316 and said armature, normally open springs 312 (now closed), armature 311 and its working contact, and resting contact of armature 322 and said armature to ground. Relay 305, upon deenergizing, at armature 314 closes a circuit for operating the rotary magnet 308; at armature 315 opens the vertical magnet circuit and prepares the release magnet circuit; and at armature 316 opens a point in the shunt circuit around itself. The circuit for energizing the rotary magnet 308 may be traced as follows: ground by way of armature 322, working contact of armature 311 and said armature, armature 314, interrupter springs 313 of the rotary magnet and through the winding of rotary magnet 308 to battery. Rotary magnet 308 energizes and interrupts its own circuit in a buzzer like manner to rotate the wipers in search of an idle trunk. Rotary magnet 308 continues to rotate the wipers over the bank contacts until an idle trunk is encountered, that is, until the wiper 327 encounters a contact having battery potential thereon.

40 Assuming that the second intermediate selector shown just to the right, is the first idle intermediate selector in this level, then there will be a battery potential on test contact 330 extending to a resistance, similar to resistance 345 in the first intermediate selector. When wiper 327 encounters the battery potential on test contact 330, switching relay 306 energizes over the following circuit: ground by way of grounded release trunk conductor 302, lower winding of switching relay 306, test wiper 327, bank contact 330, release trunk conductor 333, and over a similar circuit to a resistance, similar to 345, and battery. Relay 306, upon energizing, at armature 320 disconnects relay 305 and connects the release trunk 302 straight through to release trunk 333 and also short circuits the lower energizing winding of switching relay 306; at armature 321 completes a locking circuit for itself through its upper winding to grounded release trunk conductor 302; at armature 322 opens a

point in the circuit for the release magnet 309; and at armatures 319 and 323 disconnects the line relay 304 and connects the talking conductors 301 and 303 to the talking conductors 332 and 334, respectively. The deenergization of line relay 304 is without effect at this time other than to close a point in the circuit for the release magnet 309.

10 The second intermediate selector seized over conductors 332 to 334, being similar in all respects to the intermediate selector just described, will therefore operate in the same manner and seize an idle trunk, such as the 15 trunk comprising conductors 341 to 343, extending to an idle connector responsive to the next series of impulses.

Assuming that the connector in Fig. 5 is the connector seized, the circuit for energizing the switching relay of the second intermediate selector may be traced as follows: ground by way of grounded release trunk conductor 333, winding of switching relay, test wiper 336, bank contact 339, conductor 25 342 armature 417 and its resting contact, normally closed off-normal springs 443, and through the upper winding of relay 405 to battery and also by way of normally closed springs controlled by armature 436, and resistance 442 to battery. Relay 405 in the connector does not operate until the switching relay in the second intermediate selector 30 short circuits its upper winding, thereby permitting sufficient current flow to energize 35 relay 405.

When the second intermediate selector cuts through a circuit is completed for energizing line relay 402 of the connector as follows: from ground and battery through the upper 40 and lower windings of relays 223 and 224 of the first selector repeater by way of the circuit previously traced over conductors 301 and 303, over conductors 332 and 334, conductors 341 and 343, armatures 447 and 452 45 and their resting contacts, and through the upper windings of relays 402 and 403. Line relay 402 energizes over the above traced circuit but relay 403, being marginal, does not receive sufficient flow of current to energize. 50 Line relay 402, upon energizing, at armature 419 prepares the impulsing circuit. Relay 405, due to its mechanical construction, is slightly slow to pull up and therefore energizes shortly after line relay 402 has operated 55 armature 419. Relay 405, upon energizing, at armatures 434 and 438 disconnects interrupted generator and generator ground; at armature 435 prepares the impulsing circuit; at armature 436 disconnects the resistance 442 60 and completes a locking circuit for itself extending by way of grounded release trunk conductor 342; and at armature 437 opens a point in the circuit of the release magnet 412.

The calling subscriber may now dial the 65 next digit of the called number and accord-

ingly the line relay of the first selector interrupts the loop circuit extending to the line relay 402 of the connector. Each time the circuit of line relay 402 is opened said relay deenergizes and at armature 419 closes a circuit for operating the vertical magnet 410 as follows: ground by way of armature 435, normally closed springs controlled by armature 419, armature 448 and its resting contact, armature 430, armature 416 and its resting contact and winding of vertical magnet 410 to battery. By the operation of the vertical magnet the switch wipers 463 to 466 are operated in the well known manner opposite the desired level of bank contacts 70 in which the called line terminates. During impulsing, a circuit may be traced for slow acting relay 406 as follows: from ground by way of armature 435 by way of the previously 75 traced impulsing circuit to armature 430, and thence by way of armature 458 and its resting contact to the winding of relay 406 and battery. Slow acting relay 406, upon energizing, at armature 440 shunts the contacts 430 of the busy relay 404; at armature 441 prepares a point in the circuit for the busy relay 404; at armature 444 shunts the busy relay contacts 432; and at armature 445 opens a point in the circuit of relays 401 and 409. Upon the first vertical step of the connector, off-normal springs 420 close and complete a circuit for energizing slow acting relay 408 when line relay 402 is in energized position as follows: ground by way of armature 435, working contact of armature 419 80 and said armature, off-normal springs 420, and winding of slow acting relay 408 to battery. Relay 408, upon energizing, at armature 455 prepares a point in the circuit for relay 407; at armature 456 prepares a circuit for grounding the lower talking conductor 343; and at armature 457 prepares a circuit for energizing relay 401. At the off-normal springs 414 a circuit for the release magnet is prepared and at off-normal springs 85 443 the original energizing circuit of relay 405 is opened.

After receipt of this series of impulses slow acting relay 406 deenergizes and at armature 445 completes a circuit for energizing relay 100 401 as follows: ground by way of armature 457, armature 445, armature 433 and its resting contact, and winding of relay 401 to battery. Relay 401, upon energizing, at armature 415 prepares a locking circuit for switching relay 407; at armature 416 opens the vertical magnet circuit and prepares the rotary magnet circuit; at armature 417 opens the locking circuit of relay 405 and closes a locking circuit for itself; and at armature 418 105 opens a point in the circuit of the release magnet 412 and connects ground by way of off-normal springs 414 to replace the ground 110 which will shortly be removed at armature 435. The deenergization of relay 405 is with- 115 120 125 130

out effect at this time other than to prepare the ringing circuit.

It will now be assumed that the calling subscriber wishes to talk to any one of a group of subscribers, each having the same group call number. Assuming further that the desired group is the first group diagrammatically illustrated in Fig. 5A, the calling subscriber will then dial the group number, or in this case the digit 1. Responsive to the calling subscriber's dialling the digit 1, the line relay 402 is operated in the same manner as previously described, and upon its deenergization, responsive to the impulse, it will close at armature 419 the circuit for operating the rotary magnet. The circuit for operating the rotary magnet may be traced as follows: ground by way of off-normal springs 414, armature 418 and its working contact, normally closed springs controlled by armature 419, armature 448 and its resting contact, armature 430, armature 416 and its working contact, and winding of rotary magnet 411 to battery. The rotary magnet 411 operates the wipers in engagement with the first set of bank contacts, and wiper 464 will therefore be in engagement with test contact 480 (Fig. 5A) which has a battery potential thereon.

The operation of the rotary connector now depends upon whether the first line associated with the first set of contacts is busy or idle. If busy, there will be a ground potential on the test contact engaged by test wiper 465 and accordingly busy relay 404 energizes over the following circuit: ground by way of grounded test contact, wiper 465, armature 441 and its working contact, and winding of busy relay 404 to battery. Busy relay 404, upon energizing, at armature 429 prepares the circuit for connecting the busy tone to the calling line; at armature 431 prepares a locking circuit for itself which is completed when slow acting relay 406 falls back; at armature 433 prepares a circuit for relay 409; and at armature 432 opens the circuit to the upper winding of line relay 402 which deenergizes when relay 406 falls back. When slow acting relay 406 falls back a short interval of time after the directive rotary impulses, a circuit may be traced for energizing relay 409 as follows: from ground by way of armature 457, armature 445, armature 433 and its working contact, lower winding of relay 409, normally closed springs controlled by armature 461, test wiper 464, test contact 480, and through resistance 481 to battery. Relay 409, upon energizing, at armature 458 opens the circuit of slow acting relay 406; at armature 459 completes a locking circuit for itself extending by way of grounded test contacts accessible to test wiper 465; at armature 461 opens its original energizing circuit and closes an energizing circuit through the lower winding of relay 402; and at armature 462 grounds such armature for a purpose which will be

described hereinafter. The circuit for energizing line relay 402 may be traced as follows: ground by way of interrupter contact 413 of the rotary magnet, lower winding of line relay 402, normally open springs controlled by armature 461, and resistance 460 to battery. Line relay 402, upon energizing, at armature 419 again completes the circuit for maintaining slow acting relay 408 in energized position and also closes a circuit for operating the rotary magnet 411 as follows: ground by way of off-normal springs 414, armature 418 and its working contact, working contact of armature 419 and said armature, off-normal springs 420, working contact of armature 458 and said armature, armature 416 and its working contact, and winding of rotary magnet 411 to battery. The rotary magnet operates and steps the wipers to the next set of contacts in the desired group. Near the end of its stroke, rotary magnet 411 at armature 413 opens the circuit of line relay 402, whereupon said relay deenergizes. Line relay 402, upon deenergizing, at armature 419 opens the circuit of the rotary magnet and slow acting relay 408. If the next trunk line is busy, relay 409 will be maintained energized by way of the grounded contacts in engagement with wiper 465 and therefore, when the rotary magnet restores armature 413, the line relay is again energized and again causes the rotary magnet to step the wipers to the next set of bank contacts. This cycle of operation continues until an idle line or the last line in the group is reached.

Assuming that all the lines in the desired group are busy, the connector will rotate its wipers into engagement with the last line in the group where a ground potential will be encountered by wiper 464 which will prevent line relay 402 from again energizing. The ground on the last test contact such as 483 extends by way of wiper 464, working contact of armature 461 and said armature, through relay 402 to ground at armature 413, thereby shunting relay 402. Relay 409, however, is maintained in energized position from ground encountered by the test wiper 465. Since the line relay 402 is not again energized to close the circuit to the rotary magnet, the wipers accordingly come to rest on the bank contacts of the last line in the group. The busy tone is now transmitted to the calling subscriber by way of conductor 421, resting contact of armature 422 and said armature, armature 429, resting contact of armature 447 and said armature, to the upper talking conductor 341 from whence it is transmitted to the calling subscriber in the well known manner.

Returning to the first selector repeater, the loop circuit of relay 223 will be interrupted when the circuit through the upper winding of line relay 402 of the connector is opened by the energization and locking up of the

busy relay 404. Relay 223 accordingly de-energizes. At armature 250 relay 223 opens the locking circuit of relay 227 whereupon the latter relay releases, and at armature 268 5 relay 227 closes a point in the circuit for transmitting the busy tone to the calling subscriber. It will be noted that relay 225 is not operated and therefore said relay does not close the meter circuit at armature 256. 10 Responsive to the busy tone, the calling subscriber will replace his receiver and release the switches in the same manner as will be described hereinafter.

Assuming now that one of the group of 15 subscribers' lines, for instance subscriber A', is idle, the connector will rotate its wipers into engagement with bank contacts 467 to 470, inclusive, and since the line of substation A' is idle there will be a battery potential on test contact 469 instead of ground and therefore relay 409 will be deenergized. Relay 409, upon deenergizing, at armature 459 opens its own locking circuit and also closes an energizing circuit for switch-through relay 407 as follows: from ground by way of the lower winding of switching relay 407, resting contact of armature 459 and said armature, working contact of armature 455 and said armature, resting contact of armature 441 and said armature, wiper 465, bank contact 469, winding of switching relay 471 of line switch LS', and through the winding of rotary magnet 473 to battery. Relays 407 and 471 energize over the above-traced circuit but the stepping magnet 473 of the line switch LS' does not receive sufficient current to permit it to operatively energize. The combined switching and cut-off relay 471 of the line switch LS' disconnects the called 20 subscriber's line from battery and ground in the well known manner. Relay 407, upon energizing, at armature 447 opens a point in the circuit of the upper winding of line relay 402 causing relays 223 and 227 in the first 25 selector repeater to be deenergized in the manner previously described; at armature 448 opens the circuit to the rotary magnet; at armature 449 connects direct ground to test contact 469 and multiples thereof to render the called line busy and to hold the called line switch in operated position; at armature 450 opens the locking circuit of the 30 busy relay 404 which now deenergizes; at armature 451 closes a locking circuit for itself in series with the vertical magnet 410; at armature 452 completes the ring-back circuit through condenser 454; and at armatures 446 and 453 completes the ringing circuit 35 from interrupted generator. Due to the high resistance of the upper winding of switching relay 407 the vertical magnet does not receive sufficient current to operate. The ringing circuit for ringing the called subscriber may be traced as follows: from in-

terrupted generator INT GEN, conductor 439, lower winding of ring-cut-off relay 405, resting contact of armature 438 and said armature, armature 453, wiper 466, contact 470, over the called subscriber's line including the ringer of the called line, contact 467, wiper 463, armature 446, and armature 434 and its resting contact to ground. 70

When the called subscriber answers, ring-cut-off relay 405 is energized over its lower winding. Ring-cut-off relay, upon energizing, at armatures 434 and 438 disconnects the ringing current and completes the talking circuit; at armature 436 again completes a locking circuit for itself which extends by 75 way of the working contact of armature 448 and said armature to ground at either armatures 435 or off-normal springs 414; and at armature 437 opens a point in the circuit to the release magnet 412. 80

Returning now to the first selector repeater, it will be remembered that relay 223 de-energizes when the switching relay 407 of the connector switches through and that relay 223 opens the locking circuit of relay 227, thereby permitting relay 227 to release. As soon as the called man answers, ring-cut-off relay 405 of the connector completes a circuit for energizing relay 223 of the first selector repeater over the called subscriber's loop. Relay 223, upon energizing, at armature 250 completes an energizing circuit for slow acting relay 225 as follows: ground by way of armature 250 and its working contact, armature 270 and its resting contact, resting contact of armature 263 and said armature, and winding of slow acting relay 225 to battery. Slow acting relay 225, upon energizing, at armature 256 opens a point in the circuit to the release magnet 232 and also prepares a point in the circuit for operating the calling subscriber's meter; at armature 257 opens a point in the holding circuit for relay 223; at armature 258 completes a locking circuit for itself; at armature 259 prepares a locking circuit for relay 226; and at armature 260 prepares a circuit for grounding the lower talking conductor for supervisory purposes. Talking battery to the calling subscriber extends by way of the windings of relays 224 and 221 over the calling subscriber's loop and talking battery to the called subscriber extends through the windings of relays 224 and 223 over the called subscriber's loop. The talking circuit to the various switches may be traced by the heavy talking conductors. 105 110 115 120 125

After conversation and responsive to the called subscriber replacing his receiver, relay 223 in the first selector repeater deenergizes and prepares the metering and release circuits at armature 249 and at armature 250 opens one of the locking circuits of slow acting relay 225. 130

- When the calling subscriber replaces his receiver line relay 221 releases. Line relay 221, upon deenergizing, at armature 240 opens a point in the circuit of relay 223 and at armature 241 closes a short circuit around release relay 222, thereby rendering such relay slow to release. Before the release relay 222 deenergizes, a circuit may be traced from ground by way of armature 247, normally closed springs controlled by armature 241, armature 283 and its working contact, and through the upper winding of relay 226 to battery. Relay 226, upon energizing, at armature 261 opens a point in the circuit of line relay 221 and at armature 262 connects an additional ground to release trunk conductor 215 by way of armatures 278 and 255 to maintain the calling line switch in operated position during the metering operation.
- After an interval, release relay 222 releases and at armature 242 opens another point in the circuit of line relay 221 so that the calling subscriber can not interfere with the metering operation. At armature 244 relay 222 closes a circuit for operating the calling subscriber's meter as follows: ground by way of meter magnet M, armature 208, wiper 212, conductor 216, armature 256, armature 275, armature 244, armature 249, off-normal springs 248, and to the winding of release magnet 232 to battery. Release magnet 232 is not energized over this circuit on account of the high resistance of the meter magnet M. At armature 245 release relay 222 removes one of the ground connections from release trunk conductor 215; at armature 246 removes one of the locking grounds from the locking circuits of relays 225 and 226 as well as removing ground from release trunk conductor 302; and at armature 247 release relay 222 opens the locking circuits of relays 225 and 226. After an interval of time, relays 225 and 226 will release, it being remembered that relay 226 is slightly slow to release due to the short circuit from its lower winding. Relay 226, upon deenergizing, at armatures 262 removes ground from the release trunk conductor 215, thereby permitting the calling line switch LS to release in the well known manner. Relay 225, upon releasing, at armature 256 opens the metering circuit and closes a circuit for operating the release magnets as follows: ground by way of armature 256, armature 275, armature 244, armature 249, off-normal springs 248, and through the winding of release magnet 232 to battery. Relay 226 at armature 262 also opens the locking circuit of switching relay 229 whereupon such relay deenergizes and disconnects the talking conductor. By the operation of the release magnet 232 the first selector repeater is returned to its normal position in the well known manner, thereby

opening the off-normal springs 248 which in turn opens the circuit of the release magnet.

In case the calling man hangs up before the called man, line relay 221 will release and open the circuit of relay 223 at armature 240 so that the release of the first selector repeater is the same as if the called man had replaced his receiver.

When ground is removed from release trunk conductor 302 by the deenergization of release relay 222, relays 306 in the intermediate selectors and relay 401 of the connector deenergize. Relays 306 in the intermediate selectors, upon deenergizing, at armatures 322 close the circuit for their respective release magnets, thereby causing the release of the intermediate selectors in the well known manner.

When the combined change-over and release relay 401 in the connector releases, said relay at armature 415 opens the circuit of relay 407 in case the called subscriber has replaced his receiver. In case however, the called subscriber has not hung up his receiver a circuit for maintaining switching relay 407 energized may be traced as follows: from ground by way of upper winding of switching relay 407, armature 451, normally closed springs controlled by armature 415, working contact of armature 438 and said armature, armature 453, over the called subscriber's loop to armature 446, armature 434, armature 447 and its working contact, armature 415 and its resting contact, and winding of vertical magnet 410 to battery. Relay 407 maintains ring-cut-off relay 405 in operated position and therefore the connector does not release until the called man hangs up.

When relay 401 falls back and the called man has replaced his receiver, relay 401 at armature 415 opens the circuit of relay 407 which deenergizes. Relay 401 at armature 418 prepares the circuit for the release magnet 412. Switching relay 407, upon deenergizing, responsive to the deenergization of relay 401 or the calling subscriber replacing his receiver at armatures 446 and 453, opens the talking circuit; at armature 448 opens the holding circuit of ring cut-off relay 405 and removes ground from release trunk 342 which has been placed thereon by the deenergization of relay 401 in order to make the connector test busy as long as it is held by the called subscriber; at armature 449 removes ground from test contact 469 thereby rendering the called line idle and permitting the release of relay 471 to normal; and at armature 451 opens its own locking circuit. Ring cut-off relay 405, upon deenergizing, at armature 437 closes the circuit to the release magnet 412 whereupon said magnet releases the switch in the well known manner. All of the apparatus involved in the local connec-

tion is now released and may be used to extend other calls.

Toll call to subscriber A'

Having described the detailed operation which takes place in the establishment of a connection, subscriber A to subscriber A', we will now describe the operation which takes place when subscriber A' is desired in a toll connection. It will now be assumed that the toll operator at the switchboard shown in Fig. 1 desires to extend a connection to the line of substation A', either because he has received a long distance call for him, or because he himself has requested that a long distance connection be set up and the operator is therefore recalling him. The operations are the same in both cases. To extend the connection to the line of substation A', the operator inserts the plug of her cord circuit, for example, the plug P' of the cord circuit CC, into the jack J of a toll service trunk line terminating at her switchboard and extending to the transmission selector repeater in the local automatic exchange.

Responsive to the insertion of a plug P' into jack J a circuit may be traced for energizing the line relay 107 of the transmission selector repeater as follows: ground by way of normally closed springs controlled by armature 125, lower left hand winding of repeating coil, trunk conductor 10, ring spring of jack J, ring contact of plug P', normally closed springs of the combined dial and ringing key K¹, tip contact of plug P', tip springs of jack J, trunk conductor 9, upper left hand winding of the repeating coil in the transmission selector repeater, normally closed springs controlled by armature 123, normally closed springs controlled by armature 128, and to the lower winding of line relay 107 to battery. Polarized relay 2 is not energized over the above traced circuit because the direction of current flow is not in the proper direction. Line relay 107, upon energizing, at armature 134 prepares a circuit to the upper winding of relay 113 and also prepares the loop repeating circuit. At armature 135 relay 107 opens a point in the circuit of the release magnet 120 and closes a circuit for energizing relay 108. Release 108, upon energizing, at armature 137 prepares a holding circuit for relay 113 during impulsing; at armature 138 grounds the release trunk conductor 121; at armature 139 opens a further point in the circuit of the release magnet and prepares the impulsing circuit to the vertical magnet 118; and at armature 141 closes a circuit for energizing relay 106 by way of armature 126 and its lower winding. Relay 106, upon energizing, at armature 131 disconnects the ringing circuit and closes a circuit for energizing relays 113 and 116 in series; at armature 132 closes a shunt around armature 126 in order to maintain it-

self in energized position in case relay 102 should energize prematurely; and at armature 133 disconnects generator ground and prepares a locking circuit for the lower winding of relay 113. The circuit for energizing relays 113 and 116 may be traced as follows: ground by way of armature 150 and its resting contact, upper winding of relay 113, working contact of armature 134 and said armature, normally closed springs controlled by armature 177, armature 154, upper right hand winding of repeating coil, working contact of armature 131 and said armature, resting contact of armature 166 and said armature, armature 175, normally closed springs controlled by armature 182, and through the upper winding of relay 116 to battery. Relay 113, upon energizing, at armature 163 prepares a locking circuit for relay 116. Relay 116, upon energizing, at armature 174 prepares the dial tone circuit; at armature 175 opens a point in the original energizing circuit of relay 116; at armature 176 prepares a circuit for maintaining relay 113 energized during the impulsing period; at armature 177 opens a further point in the initial energizing circuit of relays 113 and 116 and substitutes a holding circuit for relays 113 and 116 in series; at armature 178 opens the circuit of relay 102 which does not have time to operate when the release trunk 121 was grounded because of its mechanical construction and also closes a circuit for energizing relay 114; at armature 179 opens the circuit of relay 104 and also closes a locking circuit for itself; at armature 180 opens a point in the circuit for relay 115; and at armature 181 opens the circuit of the lower talking conductor. The circuit for energizing relay 114 may be traced as follows: from ground by way of release trunk conductor 121, working contact of armature 178 and said armature, resistance 173 and winding of relay 114 to battery. Relay 114, upon energizing, at armature 165 completes the circuit for transmitting the dial tone to the operator; at armature 166 opens a point in the talking circuit; at armature 167 prepares a circuit for relay 110; and at armature 169 prepares a circuit for relay 115. Responsive to the seizure of the switch, relays 106, 107, 108, 113, 114, and 116 are operated in order to prepare the transmission selector repeater for operation.

The calling operator now throws her combined dialling and ringing key into dialling position, thereby connecting up her common calling device CD in bridge of the tip and ring conductors of the plug P'. The operator will now operate the calling device in accordance with the digits necessary to trunk the call to the line of substation A'. After the operator has dialled the complete number she will restore the combined dialling and ringing key to normal position.

Responsive to the operation of the calling

device the circuit of line relay 107 is intermittently opened and closed and said relay intermittently deenergizes and energizes responsive thereto. Each time line relay 107 falls back a circuit may be traced for operating the vertical magnet and slow acting relay 109. The circuit for energizing the vertical magnet may be traced as follows: ground by way of normally closed springs controlled by armature 135, armature 139 and its working contact, armature 182, and through the winding of vertical magnet 118 to battery. A branch of this circuit also extends through the winding of slow acting relay 109 and such relay due to its slow acting characteristics is maintained in operated position during the dialling period. At armature 134 line relay 107 closes a circuit for maintaining relay 113 in operated position during impulsing. This circuit extends by way of armature 150, the upper winding of relay 113, make before break springs controlled by armature 134, armature 137, armature 136, and through resistance 183 to battery. Slow acting relay 109, upon energizing, at armature 143 opens a point in the circuit of slow acting relay 110 and at armature 144 opens a point in the circuit for the rotary magnet 119. By the operation of the rotary magnet the switch wipers 191 to 193, inclusive, are operated opposite the desired levels of bank contacts in which an intermediate selector such as shown in Fig. 4 terminates.

A short time after the receipt of the first series of impulses slow acting relay 109 de-energizes and at armature 144 closes the circuit for rotary magnet 119 which may be traced as follows: ground by way of armature 141, armature 144, armature 140, off-normal springs 181 which were closed on the first vertical step of the switch, resting contact of armature 185 and said armature, interrupter springs 158 of the rotary magnet, and winding of rotary magnet 119 to battery.

By the operation of the rotary magnet, the switch wipers are rotated into engagement with the first step of bank contacts in the desired level. The operation of the transmission selector repeater now depends upon whether the first trunk line is busy or not. The rotary magnet will continue to operate in a buzzer like manner until the test wiper 192 encounters an idle trunk which will have a battery potential connected to its associated test contact, such as 195. Assuming that the first idle trunk encountered by test wiper 192 comprises the conductors 197 to 198 then there will be a battery potential on test contact 195 extending from the second intermediate selector through the resistance, such as 345, over conductors 333 and 198 to bank contact 195. As soon as test wiper 192 encounters the test contact 195 having battery potential thereon, switching relay 117 energizes over its upper winding from the

ground on release trunk conductor 121. Switching relay 117, upon energizing, at armature 184 shunts its upper winding and connects ground to conductors 198 and 333; at armature 185 opens the operating circuit to the rotary magnet and also closes a locking circuit for itself through its high resistance lower winding in series with the rotary magnet; at armature 186 opens the circuit to the vertical magnet 118; and at armatures 182 and 187 closes a point in the talking circuit thereby closing a circuit for energizing the line relay in the intermediate selector. The line relay of the seized intermediate selector energizes and prepares the switch for operation in the same manner as previously described. The circuit for energizing the line relay of the seized intermediate selector extends from ground by way of armature 150, upper winding of relay 113, working contact of armature 134 and said armature, working contact of armature 177 and said armature, working contact of armature 182 and said armature, wiper 191, contact 194, conductor 197, conductor 332, winding of line relay, such as line relay 304, conductor 334, conductor 199, bank contact 196, wiper 193, armature 187, armature 181 and its working contact, and through resistance 172 to battery. Relay 113 is maintained energized over the above traced circuit.

The operator may now dial the next digit of the called number and responsive thereto line relay 107 in the transmission selector repeater is operated in the same manner as previously described. Each time the circuit of line relay 107 is opened, said relay de-energizes and at armature 134 opens the circuit of the line relay in the intermediate selector. Relay 113, however, is maintained from battery through resistance 183 over the circuit previously traced. Relay 109 is again energized but does not perform any useful functions at this time.

Responsive to the interruption in its circuit, the line relay of the intermediate selector operates in the same manner as previously described to cause the intermediate selector to seize an idle trunk extending to an idle connector. Assuming that the connector shown in Fig. 5 is again seized, then line relay 402 again operates, this time from ground at armature 150 and battery through resistance 172 over the talking conductors extending between the transmission selector repeater and the connector. It will be noted that the flow of current extending over the talking conductors from the transmission selector repeater to the connector is reversed with respect to the flow of current extending over the talking conductors from the first selector repeater shown in Fig. 3 to the connector. This reversal in the direction of current flow is necessary in order to cause marginal relay 403 in the rotary connector to en-

ergize when the combined changeover and release relay 401 operates. The flow of current through the upper winding of marginal relay 403 in the proper direction to assist its winding when the connector is seized by way of a transmission selector repeater. Relay 403, however, does not at this time operate because the flow of current through the upper winding is not sufficient to operatively energize said relay. Relay 405 operates in the same manner as previously described when the release trunk conductor is grounded.

The operator may now dial the next digit in the number of the called subscriber. Responsive thereto, line relay 107 in the transmission selector repeater repeats the impulses to line relay 402 in the rotary connector, thereby operating the connector wipers opposite the desired group of bank contacts in which the called line terminates. Relays 406, 408, and 401 operate in the same manner as previously described. When relay 401 energizes after the first series of impulses, said relay closes a circuit at armature 417 through resistance 426 to the lower winding of marginal relay 403. The flow of current through both the winding of relay 403 is now sufficient to operate armature 425. Armature 425, upon closing its make contact, short circuits the resistance 426, thereby causing the marginal relay to pull all the way up and lock to the grounded release trunk conductor 342. Relay 403, upon energizing, at armature 422 opens a point in the circuit extending to the busy tone machine; at armature 423 maintains the ring-cut-off relay in energized position so that the operator may control the application of ringing current; at armature 424 disconnects direct ground so that ground through a resistance 428 will be applied to the test contact of the called line when the connector switches through; and at armature 427 prepares a circuit for grounding conductor 343.

Assuming now that the operator desires to connect with a particular line, such as substation A', in a group of lines all having the same common called number, she will therefore dial the individual call number of substation A'. Assume further that substation A' is the desired subscriber and that the line of substation A' terminates in the fourth set of contacts in the level to which the connector has been operated, the operator will therefore dial the digit 4. Responsive to the operator dialling the digit 4, the line relay in the transmission selector repeater repeats the impulses to line relay 402 in the rotary connector whereupon line relay 402 operates the rotary magnet to cause the wipers to come to rest in engagement with the fourth set of bank contacts in the selected level, or the bank contacts individual to the called subscriber A'.

Since only the first contact in a group has

battery potential on test contacts such as contacts 480 and 485, (Fig. 5A) relay 409 will not be energized because its circuit is opened at armature 445 when wiper 464 passes over the first contact in the group.

Assuming now that substation A' is idle, switching relay 407 will energize in series with switching relay 471 of the called line switch LS' in the same manner as previously described. Switching relay 407, upon energizing, at armature 447 opens the circuit of line relay 402; at armature 448 opens the rotary magnet circuit; at armature 449 connects ground through resistance 428 to test contact 469 thereby applying a discriminating ground potential instead of direct ground; at armature 451 locks itself in series with the vertical magnet 410; and at armatures 446 and 453 connects up the talking conductors. Line relay 402, upon deenergizing, at armature 419 opens the circuit of slow acting relay 408. After an interval, slow acting relay 408 deenergizes and at armature 456 prepares a point in the circuit for the lower winding of switching relay 407.

Returning now to the toll transmission selector, the circuit of relay 113 is opened when switching relay 407 of the connector opens the loop at armature 447 and accordingly relay 113 deenergizes. Relay 113, upon deenergizing, at armature 163 opens the locking circuit of relay 116 whereupon the latter relay deenergizes. Relay 116, upon deenergizing, at armature 174 prepares the busy circuit; at armatures 175 and 181 prepares the talking circuit; at armature 176 opens a point in the holding circuit of relay 113; at armature 177 disconnects relay 113 from wiper 191; at armature 178 opens the circuit of relay 114 and completes a circuit for relay 102; at armature 179 prepares a point in the circuit for relay 104; and at armature 180 closes the circuit for energizing relay 115 which energizes and causes slow acting relay 109 to energize also. After a short interval of time, relay 114 deenergizes and at armature 165 opens the busy tone circuit; at armature 166 completes the talking circuit; at armature 167 prepares a point in the circuit for relay 110; and at armature 169 opens the circuit of relay 115 which deenergizes and causes relay 109 to deenergize. A short interval of time after its circuit is closed, relay 102 energizes and at armature 122 prepares the ringing circuit. At armature 126 relay 102 opens a point in the holding circuit of relay 106 which is held up, however, over the back contacts of the A. C. relay 105; at armature 124 completes the circuit for the A. C. relay 105; and at armatures 123 and 125 reverses the flow of current over trunk conductors 9 and 10 so that the polarized relay 102 in the cord circuit CC operates to light the lamp L when the operator restores the dial key.

By the operation of the lamp L, the op-

erator knows that the called line is idle, and accordingly momentarily operates her ringing key K^1 , thereby applying generator to trunk conductors 9 and 10. A. C. relay 105 operates responsive thereto and opens the locking circuit of relay 106 which accordingly deenergizes. Relay 106, upon deenergizing, at armatures 131 and 133 connects the generator to the called line. The ringing circuit extends by way of generator GEN, conductor 190, armature 122, upper winding of relay 106, resting contact of armature 131 and said armature, over the heavy talking conductors to the called subscriber's line and thence back to ground at armature 133. Responsive to the operation of this bell, the called subscriber will remove his receiver, thereby causing the operation of ring-cut-off relay 106 over the previously traced ringing circuit. Relay 106, upon energizing, at armature 132 again closes its locking circuit and at armatures 131 and 133 completes the talking circuit and also completes a circuit for energizing the battery feed relay 113 over the called subscriber's loop. Relay 113, upon energizing, at armature 163 completes an obvious circuit for energizing relay 104. Relay 104, upon energizing, at armatures 128 and 129 disconnects all battery and ground connections from the trunk conductors 9 and 10 thereby providing a dry trunk in order to improve the talking circuits and also at armature 128 closes a local holding circuit for the two windings of relay 127 in series. When the battery and ground connections are cut off from the trunk conductors 9 and 10, polarized relay 2 in the cord circuit deenergizes and puts out the lamp, thereby signalling the operator that the called man has answered. The talking circuit may be traced over the heavy talking conductors in the well known manner.

After conversation and responsive to the called subscriber replacing his receiver, relay 113 in the transmission selector repeater deenergizes and at armature 163 opens the circuit of relay 104. Relay 104, upon deenergizing, again connects battery and ground to the trunk conductors 9 and 10 thereby operating the polarized relay 2 in the cord circuit to light the lamp L. The operator, upon perceiving the lighted condition of the lamp L, will remove the plug P' from the jack J, thereby opening the circuit of line relay 107. Line relay 107, upon deenergizing, at armature 135 opens the circuit of release relay 108 which thereupon deenergizes. At armature 138, release relay 108 removes ground from release trunk conductor 121 thereby causing the release of relay 117 and the release of the intermediate selector and connector as previously described. At armature 141, slow to release relay 108 opens the locking circuit of ring-cut-off relay 106 and at armature 139 closes a circuit for energizing the release magnet 120. By the operation of the release magnet 120 the transmission selector repeater is returned to its normal position in the well known manner.

Having described the operation which takes place in establishing a toll call to an idle subscriber's line, an explanation will now be given of the operation which takes place when the operator wishes to complete a toll connection to a subscriber's line which is busy in an established local connection. It will now be assumed that substation A' is the called party in an established local connection and that the toll operator wishes to establish a connection to such party.

The operation of the apparatus will be the same as described up to the time that the connector shown in Fig. 5 comes to rest with its test wiper 465 in engagement with test contact 469 or multiples thereof. Since substation A' is busy in a local connection there will be a direct ground potential on test contact 469 and multiples thereof and accordingly the busy relay 404 of the connector will be energized and locked up as previously described. In this case, however, the circuit to the upper winding of relays 402 and 403 are opened at armature 432 of the busy relay and accordingly line relay 402 releases while the marginal relay 403 is maintained energized over its lower winding. Line relay 402, upon deenergizing, at armature 419 opens the circuit of slow acting relay 408 which now deenergizes. Relay 408, upon deenergizing, at armature 455 grounds the upper talking conductor 341 as follows: direct ground encountered by test wiper 465, armature 441, armature 455, armature 422, armature 429, armature 447, and conductor 341. At armature 456 relay 408 connects the lower winding of relay 407 to conductor 343 as follows: ground through the lower winding of relay 407, armature 456, armature 427, armature 432, armature 452, and conductor 343.

Returning now to the toll transmission selector, relay 113 deenergizes when ground through the lower winding of relay 407 is connected to conductor 343 in place of the line-relay bridge. Relay 113 deenergizes slowly because its upper winding is shunted. The shunt circuit may be traced as follows: from grounded conductor 343, contact 338, wiper 335, conductor 332, conductor 197, contact 194, wiper 191, armature 182, armature 177 and its working contact, armature 134, and upper winding of relay 113 to ground at armature 150. Relay 113, upon deenergizing, at armature 163 opens the locking circuit of relay 116 which relay thereupon deenergizes. Relay 116, upon deenergizing, and at armature 175 completes a circuit for maintaining relay 114 in operated position. This circuit extends from ground through the lower winding of relay 407, over the circuit previously traced to armature 175 and

thence by way of armature 166, resistance 173 and winding of relay 114 to battery. Relay 407 of the connector is not energized over this circuit on account of the combined resistances of the winding of relay 114 and resistance 173. A circuit may now be traced by way of the direct ground on said contact 469, or multiples thereof, to conductor 341 from whence it extends by way of bank contact 340, wipers 337, conductor 334, conductor 199, contact 196, wiper 198, armature 187, armature 181, armature 169 and its left hand working contact, and winding of relay 115 to ground. This direct ground extending from test contact 469 shunts relay 115 thereby preventing the operation of relay 115. A busy tone circuit may now be traced by way of conductor 148, armature 142, armature 174, armature 165, armature 131 and its working contact, and from thence over the heavy talking conductors to the operator's head set in the cord circuit. The busy tone applied by way of conductor 148 indicates to the calling operator that substation A' is busy in a local connection.

In case the operator desires to cut in on the established local connection she will operate the key K^2 , thereby grounding conductors 9 and 10 in an obvious manner. Responsive to grounding conductors 9 and 10, differential relay 103 is now energized. Relay 103, upon energizing, closes a circuit for energizing slow acting relay 110 as follows: ground by way of armature 163 and its resting contact, armature 143, armature 167, armature 127, and winding of relay 110 to battery. Relay 110, upon energizing, at armature 149 operates the two-step relay 111 in its first step; at armature 150 closes a locking circuit for itself as long as relay 103 is energized; at armature 152 opens a point in the circuit of the lower winding of relay 113; and at armature 153 prepares a point in the circuit for grounding conductor 199. At armature 151, relay 110 connects battery potential by way of the low resistance winding of rotary magnet 119 to the winding of relay 114 and thence by way of resistance 173 to conductor 197. The connection of this battery potential shunts relay 114 thereby causing said relay to deenergize and also causes the switching relay 407 in the connector to energize over the circuit previously traced through its lower winding. Two-step relay 111, upon energizing in its first step, operates only armatures 156 and 157. At armature 156 relay 111 closes a circuit from ground at armature 141 through both its windings in series to battery. Relay 111, however, will not energize over this circuit because the lower winding is shunted by ground at armature 149. At armature 157, relay 111 closes a shunt around the contacts of armatures 167 thereby preparing a new circuit for holding relay 110 when slow act-

ing relay 114 deenergizes. When slow-acting relay 114 finally falls back, said relay at armatures 166 and 169 prepares the talking circuit.

Returning now to the connector and when relay 407 energizes over the above-traced circuit from the transmission selector repeater, said relay at armatures 446 and 453 closes the talking circuit; at armature 447 disconnects conductor 341 from grounded contact 469; at armature 449 connects ground through discriminating resistance 428 to test contact 469; at armature 450 opens the circuit to the busy relay 404 which deenergizes; at armature 451 completes a locking circuit for itself in series with the vertical magnet; and at armature 452 disconnects the lower winding of relay 407 from conductor 343. At this time only relays 401, 403, 405, and 407 of the connector are in operated position.

In the transmission selector repeater differential relay 103 deenergizes when the operator restores the key K^2 and said relay opens the circuit of slow acting relay 110. Slow acting relay 110, upon deenergizing, removes ground from armature 149, thereby permitting the two step relay 111 to fully operate to its second step. Two-step relay 111, upon energizing in its second step, at armature 154 opens the circuit to the upper winding of relay 113; at armature 155 prepares the circuit for operating the two step relay 112 in its first step; at armature 158 opens a point in the circuit extending to the lower winding of relay 113; and at armature 159 prepares a circuit for grounding conductor 199.

The operator may now converse with the desired subscriber and inform him of the desired toll connection. In case the operator desires to break down and release the local connection she may do so by again operating the key K^2 , thereby again connecting ground to conductors 9 and 10 to cause the differential relay 103 to operate. Relay 103, upon energizing, closes a circuit for energizing relay 110 as follows: ground by way of armature 163 and its resting contact, armature 143, armature 157, armature 127, and winding of relay 110 to battery. At armature 153 relay 110 grounds conductor 199 and at armature 149 completes an obvious circuit for energizing two-step relay 112 in its first step. Two-step relay 112 does not operate in its second step when it closes armature 161 because of the shunt circuit around its lower winding. Two-step relay 112 operates only armatures 160 and 161 in its first step and therefore a circuit may be traced from ground by way of armature 163 and its resting contact, armature 143, armature 157, armature 145, armature 160, working contact of armature 131 and said armature, armatures 166, 175, and 182 to conductor 197.

Assuming now that the first selector repeater shown in Fig. 3 is the first selector repeater in the local connection about to be broken down, then when ground is connected to conductors 197 and 199 at the toll transmission selector the differential relay 224 in such selector repeater will operate. Ground on conductor 199 extends over the talking conductors 334, 341, bank contact 467 and multiples thereof to the connector wiper, such as wiper 463, in the local connection, back over the talking conductors such as 341, 334, 303, and through the lower winding of relays 223 and 224 to ground. Another circuit extends by way of grounded talking conductor 197, conductors 332, 343, bank contact 470 and multiples thereof to the connector wiper such as wiper 466 of the connector in use in the local connection, back over the conductors, such as conductors 343, 332, 301, and through the upper winding of relays 223 and 224 to battery. Differential relay 224, upon energizing over the above traced circuits, at armature 254 closes an energizing circuit for relay 228; at armature 253 closes an energizing circuit for the release magnet 232 from grounded release trunk conductor 215 thereby causing the first selector repeater to release; and at armature 255 opens a point in the circuit to the rotary magnet. Relay 228, upon energizing, at armatures 273 and 279 opens the circuit of relays 221, 222, and 224, and also cuts the talking conductors straight through; at armature 275 opens the metering circuit; at armature 276 completes a locking circuit for itself by way of grounded release trunk conductor 215; and at armature 278 prepares a circuit for momentarily grounding wiper 291. Line relay 221, upon deenergizing, at armature 241 opens the circuit of release relay 222 and also closes a short circuit around the same. At the normally closed springs controlled by armature 241, relay 221 completes a circuit for energizing relay 226. Relay 223, upon releasing, at armature 249 closes a point in the metering circuit which, however, at this time, is opened at armatures 275 and 244; and at armature 250 opens one of the locking circuits for relay 225. Relay 224, upon deenergizing, at armature 253 opens the release magnet circuit, the switch releasing, however, due to the mechanical construction of the release link; and at armature 254 opens the initial energizing circuit of relay 228. Relay 226, upon energizing, at armature 261 opens a further point in the circuit of line relay 221. After an interval of time for which it is adjusted, release relay 222 deenergizes and at armature 245 removes ground from release trunk conductor 215 thereby permitting the line switch LS to restore. At armature 245 relay 222 also opens the circuit of relays 228 and 229 which also deenergize. At armature 246 release relay 222 opens the circuits of relays 225 and 226 and removes ground from conductor 302, thereby permitting the intermediate selector and the connector in the local connection to release in the manner described. At armature 247 release relay 222 opens another point in the circuit of relays 225 and 226. Relays 228 and 229 release and relay 228 and armature 275 prepares the metering circuit, but by this time the first selector repeater has released and the off-normal springs 248 are opened and therefore the meter M of the calling subscriber will not be operated, even if relay 225 at armature 256 has closed the metering circuit. After an interval of time relays 225 and 226 release and the first selector repeater is therefore in normal position.

When ground is removed from the release trunk conductor 215, line switch LS releases in the usual manner and immediately reoperates to either seize the same selector repeater or another selector repeater. The calling subscriber A after being cut off will hang up and restore the line switch and seized selector repeater to normal.

The application of ground through the discriminating resistance 428 of the rotary connector in the subscriber's toll connection maintains the combined switching and cut-off relay 471 of the called line switch LS in operated position.

Before continuing with the description of a completed toll connection it may be best to consider the operation which takes place when the toll operator wishes to complete a toll connection to subscriber A when subscriber A is the calling party in an established local connection. In this case the toll operator in operating the connector switch to the line of the desired subscriber, such as A, desired in a toll connection, the connection would therefore be extended by way of the connector over the normal conductors, such as conductors 201, 202, and 218. The operation of the switches in the toll train would be the same as previously described and the operator would be able to talk to the subscriber over conductors 201 and 202. In order to break down and release the local connection the operator again operates the key K² and grounds conductors 202 and 201. The calling line switch LS is held in the usual manner by ground extending through the resistance 428 to conductor 218. When ground is connected to conductors 201 and 202, differential relay 224 in the first selector repeater in the local established connection energizes over the following circuits: ground by way of conductor 201, armature 206, conductor 214, armature 273 and its resting contact, armature 242, through the upper windings of relays 221 and 224 to battery. Another circuit extends from grounded conductor 202 by way of armature 209, armature 217, armature 279, through the lower windings of relays 221 and 224 to ground. Differential re-

lay 224 energizes over the above-traced circuit and causes the first selector repeater to operate in the same manner as previously described except that in this case relays 228 and 229 are held energized from ground extending from the connector over conductor 218. Relay 228 is held energized in order to disconnect battery and ground in the selector repeater from the line of substation A.

5 Before completing the toll connection after the break-down of a local connection, the operation which takes place when the toll operator desires to complete a connection to a subscriber's line engaged in another toll connection should be considered. It will be remembered that the connector applies ground to the test contact of the called line through a discriminating resistance such as 428. Therefore, when the operator extends the connection into engagement with the subscriber's line this discriminating ground potential extends by way of conductor 199 over the circuit previously traced to relay 115. In this case, the discriminating resistance is not high enough to shunt relay 115 and accordingly relay 115 operates when relay 116 deenergizes. Relay 115, upon energizing, at armature 171 closes a circuit for energizing slow acting relay 109. Relay 109, upon energizing, at 10 armature 142 disconnects the local busy tone and connects in place thereof the toll busy tone which extends by way of conductor 147. At armature 143 relay 109 opens the circuit of relay 110 so that the operator cannot operate it responsive to the operation of the break-down key K². Since relay 110 can not be operated, relay 114 will be maintained energized and relay 407 of the connector can not, therefore, be energized. The toll operator is therefore unable to operate the switching relay 407 of the connector and is unable to cut in on the toll connection. By the completion of the toll busy circuit, the operator knows that the desired subscriber is engaged in a toll connection and that she can not therefore cut in on such a connection.

Returning now to the completion of the desired toll connection after the local connection has been broken down, the operator 50 will restore the key K², thereby causing the differential relay 103 in the transmission selector repeater to deenergize and open the circuit of relay 110. Relay 110, upon deenergizing, at armature 149 permits the two-step relay 112 to operate in its second step, the circuit extending by way of armature 163, armature 143, armature 157, and armature 161 through the two windings in series to battery. At armature 153 relay 110 removes ground from conductor 199. Two-step relay 112, upon energizing in its second step, at armature 145 removes ground from conductor 197 and at armature 162 opens the locking circuit of two-step relay 111 which deenergizes. Two step relay 111, upon de-

energizing, at armature 157 opens the circuit of two-step relay 112 which also deenergizes.

The transmission selector and connector are now in the same condition as when the toll connection had been completed to an idle line and therefore the operator will ring the called subscriber and the connection will be completed in the same manner as previously described.

Local connection to distant automatic Exchange E

Having described how local connections and toll connections are established, a description will now be given of the operation which takes place when a subscriber such as A calls a subscriber in the distant automatic exchange.

Assume now that substation A desires to call a subscriber in the distant automatic exchange. Subscriber A will remove his receiver and will dial the digits of the called number necessary to route the call to the distant automatic exchange. The line switch LS and the first selector repeater are operated in the same manner as previously described except that the first selector repeater selects an idle trunk to the distant automatic exchange instead of a trunk to a local intermediate selector. It will be further assumed, in this case, that the trunk comprising conductors 601 and 602 is the trunk seized by the first selector repeater. Switching relay 229, therefore, energizes in series with the upper winding of the two step relay 501 of the trunk meter relays by way of test contact 292 and conductor 295. Two-step relay 501 does not energize on account of the high resistance of relay 229. However, when switching relay 229 at armature 282 connects ground to conductor 295 two-step relay 501 operates in its first step and operates only the armature 508. Two-step relay 501, upon energizing in its first step, at armature 508 shunts its lower winding from ground at armature 518 as well as preparing an energizing circuit from ground at armature 518 through the two windings in series for energizing such relay in its second step. The operation of two-step relay 501 prepares the trunk meter relays for operation.

When switching relay 229 in the first selector repeater switches through a circuit is closed for energizing relay 605 in the incoming selector repeater in the distant automatic exchange as follows: from ground by way of the lower windings of relays 224 and 223, wiper 292, conductor 296, trunk conductor 602, normally closed springs controlled by armature 634, normally closed off-normal springs 621, upper winding of relay 605, trunk conductor 601, armature 506, conductor 294, wiper 290, and from thence through the upper winding of relays 223 and 224 to battery.

Relay 605, upon energizing, at armature 620 causes the energization of line relay 604. Relay 604, upon energizing, at armature 618 closes a circuit for energizing relays 607 and 609 in series; and at armature 619 closes a circuit for energizing release relay 603 as follows: ground by way of armature 619, winding of release relay 603, armature 636 and its resting contact; and through the winding of vertical magnet 611 to battery. The vertical magnet is not energized over this circuit on account of the high resistance of relay 603. Relay 603, upon energizing, at armature 614 prepares a circuit for holding relay 607 energized during the impulsing period; at armature 615 closes a locking circuit for itself and prepares the impulsing circuit; and at armature 616 opens the circuit to release magnet 613 and prepares a circuit for grounding test wiper 644. The circuit for energizing relays 607 and 609 may be traced as follows: ground by way of the lower winding of relay 609, normally closed springs controlled by armature 634, armature 618 and its working contact, upper winding of relay 607, and upper winding of relay 608 to battery. Relay 608, being differential, is adjusted so that it will not operate over this circuit. Relay 607, upon energizing, at armature 623 completes a locking circuit through the upper winding of relay 609. Relay 609, upon energizing, at armature 630 opens a point in the talking circuit; at armature 631 closes a further point in the circuit for maintaining relay 607 operated during the impulsing period; at armature 633 closes a locking circuit through its upper winding; and at armature 634 completes a loop circuit through the upper winding of line relay 604 in place of the loop circuit through the upper winding of relay 605. Relay 605 accordingly deenergizes and opens the original energizing circuit of relay 604. Relay 604, however, does not deenergize because it is held in energized position over the loop including the trunk conductors 601 and 602.

The calling subscriber may now dial the next digit of the called number. The first selector repeater repeats the impulses in the same manner as previously described and in this case causes relay 604 to deenergize for each interruption in the loop circuit. Each time line relay 604 falls back responsive to the interruptions in its loop circuit, said relay at armature 619 short circuits release relay 603 so as to render such relay slow to release and closes a circuit for operating relay 606 and the vertical magnet 611. At armature 618 line relay 604 closes the holding circuit for relay 607. The circuit for energizing relay 606 and the vertical magnets may be traced as follows: ground by way of armature 615, normally closed springs controlled by armature 619, through the two windings of relay 606 to battery and by way of armature 636 through the winding of the vertical magnet 611 to battery. Relay 606 at armature 222 opens a point in the rotary magnet circuit so that the rotary magnet will not operate after the off-normal springs close on the first vertical step of the switch. Relay 606 is slightly slow to release because of the small flow of current through relays 603 and 606 in series when relay 604 is energized. This flow of current is only sufficient to make relay 606 slow acting during impulsing. By the operation of the vertical magnet the switch wipers 643 to 645, inclusive, are operated opposite the desired level of bank contacts. Shortly after the impulses cease, relay 606 falls back and at armature 622 closes a circuit for operating the rotary magnet 612. The circuit for energizing the rotary magnet may be traced as follows: ground by way of armature 616 and its working contact, armature 622 and its resting contact, off-normal springs 642 which were closed on the first vertical step of the switch, resting contact of armature 638, interrupter springs 641 of the rotary magnet, and winding of rotary magnet 612 to battery. The rotary magnet energizes and rotates the wipers on to the first step of bank contacts. Near the end of its stroke the rotary magnet interrupts its own circuit at interrupter springs 641. In case the first trunk is busy rotary magnet 612 operates in a buzzer-like manner until an idle trunk is reached. The switch continues to rotate over grounded or open contacts accessible to test wiper 644 until a test contact is encountered which has a battery potential thereon. Assuming that the trunk line terminating in bank contacts 646 to 648, inclusive, is the first idle trunk line encountered by the switch wipers, then test contact 647 will have battery potential connected thereto from an idle intermediate selector. When battery potential is encountered on test contact 647 by wiper 644, switching relay 610 is operated over the following circuits: ground by way of armature 616 and its working contact, upper winding of switching relay 610, armature 627, test wiper 644, test contact 647, and through a resistance, similar to resistance 345 in the intermediate selector shown in Fig. 4, to battery. Switching relay 610, upon energizing, at armature 636 opens the vertical magnet circuit and short circuits the lower winding of relay 606; at armature 637 disconnects direct ground to test contact 647 and short circuits its upper winding; at armature 638 completes a locking circuit for itself through its lower winding in series with the rotary magnet and also opens the circuit to the rotary magnet to stop the wipers on the idle trunk; and at armatures 635 and 639 prepares a loop circuit for the line relay of the seized intermediate selector whereupon such selector is prepared for operation in the same manner as previously described. The

loop energizing circuit for the line relay of the seized intermediate selector may be traced as follows: from ground through the lower windings of relays 608 and 607, armature 639, wiper 645, contact 648, through the line relay of the intermediate selector, contact 646, wiper 643, armature 635, armature 618, and through the upper windings of relays 607 and 608 to battery. Relay 607 is maintained energized over this circuit but relay 608, being differential, will not energize.

Responsive to dialling the next series of impulses the first selector repeater repeats the impulses in the same manner as previously described. Each time the loop over conductors 601 and 602 is interrupted, line relay 604 deenergizes and at armature 618 opens the loop circuit of the line relay of the seized intermediate selector. During impulsive relay 606 is again energized by way of armatures 619 and 636 and said relay at armature 622 connects direct ground to the lower talking conductors to improve impulsive. Responsive to the interruption in its loop circuit, the line relay of the intermediate selector is operated to cause the intermediate selector to seize an idle connector in the same manner as previously described for the intermediate selector shown in Fig. 4.

30 The next two series of impulses dialled by the calling subscriber will be repeated by the first selector repeater and the incoming selector repeater to cause the seized connector to extend the connection to the desired line in 35 a manner similar to the manner described for the connector shown in Fig. 5.

Assuming now that the called subscriber in the distant automatic exchange is busy when called, then the busy relay, such as relay 404, will energize and connect the busy tone to its upper talking conductor from whence it will be transmitted to the calling subscriber in the well known manner. It will be remembered that when busy relay 404 energizes, it opens the loop extending to the connector at its armature 432. In this case busy relay 404 of the connector will open the circuit of relay 607 in the incoming selector repeater thereby causing such relay to de- 45 energize. At armature 623 relay 607 opens the locking circuit of relay 609 whereupon the latter relay deenergizes. Relay 609, upon deenergizing, at armature 630 closes a point in the busy circuit; at armature 631 55 opens a point in the holding circuit for relay 607; and at armature 634 opens the circuit of line relay 604 and at the make-before-break contacts controlled by armature 634 substitutes the upper low resistance winding 60 and the lower high resistance winding in 60 series across the trunk conductors 601 and 602 in place of the upper winding of line relay 604. Relay 605 energizes and at armature 620 maintains line relay 604 in oper- 65 ated position. Due to the high resistance of

the lower winding of relay 605, relay 223 in the first selector repeater deenergizes. The first selector repeater remains in this position until the calling subscriber replaces his receiver responsive to his hearing the well known busy tone. It will be noted that since relay 223 is not again energized no current is supplied for energizing relay 225 and accordingly relay 225 does not energize to close the meter circuit at armature 256. When the calling subscriber replaces his receiver the first selector is released as soon as the release relay 222 is deenergized. The trunk meter relays start to operate when ground is removed from conductor 233 in a manner which will be described hereinafter. The operation of the trunk meter relays, however, are without effect at this time because the first selector repeater has released and therefore no circuit is supplied for operating the calling subscriber's meter.

Assuming now that the called subscriber in the distant automatic exchange is idle when called, then switching relay 407 energizes and opens the circuit of relay 607 at 90 armatures 447 and 452. The release of relay 607 causes the deenergization of relay 609 and the energization of relay 605 in the same manner as previously described.

Returning to the first selector repeater, relay 223 deenergizes when the two windings of relay 605 are substituted for the upper winding of relay 604. The deenergization of relay 223 causes the deenergization of relay 227 and therefore the first selector repeater switches over from impulsive to talking position in the same manner as previously described.

When the called subscriber in the distant automatic exchange answers responsive to 105 ringing current transmitted from the connector, relay 607 is energized over the called subscriber's loop as follows: from ground by way of the lower windings of relays 608 and 607, armature 639, wiper 645, over the called subscriber's loop including the intermediate selector and connector, wiper 643, armature 635, and its working contact, armature 618 and its working contact, and through the upper winding of relays 607 and 608 to battery. Relay 607, upon energizing, at armature 224 short circuits the lower high resistance winding of relay 605, thereby causing relay 223 of the first selector repeater to energize. The short circuit around the lower 110 winding of relay 605 includes armature 624, normally closed springs controlled by armature 630, and normally closed springs controlled by armature 634.

In the first selector repeater the energization of relay 223 causes the meter control relay 225 to energize and prepare the talking circuit at armature 256. Talking battery to the calling subscriber is furnished by the first selector repeater as previously described 120 125 130

while talking battery to the called subscriber is furnished through relays 607 and 608 in the incoming selector repeater.

After conversation, the called subscriber will replace his receiver thereby causing the deenergization of relay 607. Relay 607 at armature 624 opens the short circuit around the lower high resistance winding of relay 605, thereby including such high resistance winding in bridge of the trunk. Responsive to this relay 223 in the first selector repeater deenergizes and opens one of the locking circuits of relay 225 which, however, is locked up in energized position from ground at armature 246.

When the calling subscriber replaces his receiver, line relay 221 of the first selector repeater deenergizes and prepares a circuit for releasing the switch in the same manner as previously described. However, since the call was extended to a subscriber's line in the distant automatic exchange, the first selector repeater is prevented from releasing until the meter of the calling subscriber has been operated the correct number of times. Line relay 221, upon deenergizing, at armature 241 short circuits release relay 222 and causes relay 226 to operate. Relay 226, upon energizing, at armature 262 grounds the release trunk conductor 215 to hold the line switch and relay 229 in operated position. After an interval of time relay 222 releases and removes ground from conductor 233.

Referring now to Fig. 6 and when release relay 222 removes ground from conductor 233, two-step relay 501 is operated in its second step responsive to the ground being removed from conductor 233. Two-step relay 501, upon energizing, at armature 506 opens the trunk to the incoming selector repeater thereby permitting the operated switches in the distant automatic exchange to release in an obvious manner. At armature 507 two-step relay 501 grounds conductor 295 thereby maintaining relays 225 and 226 in energized position. At armature 509 two-step relay 501 closes a circuit for energizing slow to release relay 502 and at armature 510 prepares a circuit for operating relay 223 of the first selector repeater. Relay 502, upon energizing, at armature 511 causes the energization of relay 503. Relay 503, upon energizing, at armature 512 closes a circuit for energizing two-step relay 504 in its first step; at armature 513 opens the circuit of slow-acting relay 502; and at armature 514 connects battery potential to conductor 296. Two-step relay 504 operates only armature 517 in its first step, thereby preparing a circuit through both its windings in series for operating itself in its second step when ground is removed from armature 512. After an interval of time, slow acting relay 502 releases and opens the circuit of relay 503 which releases after a certain time interval.

Relay 502 is slow to deenergize and relay 503 is slow to pull up as well as slightly slow to fall back. These relays now operate as interrupter relays to operate the two-step relays 504 and 505. When relay 503 falls back, said relay at armature 512 permits two-step relay 504 to operate in its second step; and at armature 513 again closes a circuit for relay 502; and at armature 514 removes the battery potential from conductor 296. Two-step relay 504, upon energizing in its second step, operates armature 516 thereby preparing the circuit of two-step relay 505. Relays 502 and 503 again operate and relay 503 at armature 514 again connects battery potential to conductor 296. At armature 512 relay 503 causes two-step relay 505 to operate in its first step and at armature 519 the latter relay prepares a circuit through its two windings in series in order to operate itself through its second step. At the resting contact of armature 519 relay 505 opens the circuit of two-step relay 504 and said relay accordingly deenergizes. Relay 504, upon deenergizing, at armature 516 disconnects ground at armature 512 from the middle point of the two windings of two-step relay 505 thereby permitting such relay to energize in its second step. At armature 518 two-step relay 505 opens the locking circuit of two-step relay 501, thereby permitting such relay to deenergize. Relay 501, upon deenergizing, at armature 507 removes ground from conductor 295 and substitutes battery through the upper winding or relay 501 in place thereof; at armature 508 opens its own locking circuit; and armature 509 opens the circuits of relays 502 and 505 which accordingly deenergize. At armature 510 relay 501 also disconnects the battery potential from conductor 296. The trunk meter relays have sent two battery impulses over conductor 296 and are now in normal position.

Returning now to the first selector repeater, relays 225 and 226, which are slow to release, are maintained operated from ground extending back over conductor 295. Each time battery potential is connected to conductor 296 by relay 503 of the trunk meter relays, relay 223 energizes over the following circuit: from ground by way of the lower winding of relays 224 and 223, normally closed springs controlled by armature 279, armature 284, wiper 292, contact 293, conductor 296, armature 510, armature 514, and resistance 515 to battery. Relay 223 at armature 249 interrupts the metering circuit thereby causing the meter M to be operated once for each operation of relay 223. The calling subscriber is prevented from interfering with the metering operation because the circuit of line relay 221 is opened at armatures 242 and 261. When ground is removed from conductor 295 by the release of relay 501, relays 225 and 226 release and

cause the release of the first selector repeater and calling line switch LS in the same manner as previously described. All apparatus is now in normal position and may be used for extending other calls.

Having described how the toll operator can break down local connections, a description will now be given of the operation which takes place when the toll operator wishes to break down a connection in which a subscriber, such as subscriber A, has completed an automatic connection to a called subscriber's line in the distant automatic exchange. In case a toll operator desires to complete a toll connection to subscriber A when such subscriber is the calling subscriber in an established connection to a distant automatic exchange, relays 224 and 228 are energized when the operator operates key K² and relay 228 prevents the 10 operation of the meter in the same manner as previously described for the break down of the local connection.

The operation, however, is slightly different when a toll operator desires to complete 25 a connection to a called subscriber in the distant automatic exchange when such subscriber is busy in a call originating from the local automatic exchange. A detailed description will now be given of the operation which takes 30 place when a toll operator wishes to complete a toll connection to the called subscriber in the distant automatic exchange when such subscriber has been called by a calling subscriber, such as subscriber A, in the local automatic exchange. The toll operator will operate the transmission selector repeater in the distant automatic exchange in the same manner as described for the transmission selector repeater shown in Fig. 2. If the toll 35 operator wishes to break down the connection she will connect ground to the multiples of the called line. The ground connections to the multiples of the called line extend back over the established connection to contacts 646 and 648 with which the wipers 643 to 645 of the incoming selector repeater are in engagement. Responsive to this, differential relay 40 608 energizes. Differential relay 608, upon energizing, at armature 627 removes ground from wiper 644, thereby permitting the succeeding switches to the called subscriber's line to release in the well known manner; at armature 628 closes a locking circuit for itself in series with relay 607 independent of ground 45 extending from contact 646; and at armature 629 closes a new holding circuit for line relay 604 which may be traced as follows: from ground by way of the lower winding of relays 224 and 223, conductor 296, conductor 50 602, normally closed springs controlled by armature 630, armature 629, and to the lower winding of line relay 604 to battery. Relay 223 of the first selector repeater is held energized over this circuit so that when battery 55 potential is applied to conductor 296 by the

trunk meter relays this battery potential will have no effect on relay 223.

When the calling subscriber A realizes that his established connection to the distant automatic exchange has been broken down by a toll operator he will therefore replace his receiver. Line relay 221 in the first selector repeater accordingly deenergizes and prepares the first selector repeater for release. The operation of the relays in the first selector repeater and trunk meter relay group is the same as previously described, except that in this case relay 223 is maintained energized from battery through the lower winding of line relay 604. Relay 223, therefore, does not send impulses for operating the meter M responsive to the operation of the trunk meter relays. After the trunk meter relays perform their cycle of operation relay 501 deenergizes and removes ground from conductor 295, thereby permitting the deenergization of relays 225 and 226 and 229 and the line switch LS. When switching relay 229 deenergizes, the holding circuit of relay 223 is opened and said relay releases. The meter M is not operated at this time because relay 203 of the line switch is deenergized or because the meter circuit is opened at armature 256. When relay 225 releases it causes the operation of release magnet 223 to release the first selector repeater in the well known manner.

Line relay 604, upon deenergizing, at armature 618 opens the holding circuit of relays 607 and 608 which thereupon release, and at armature 619 opens the circuit of release relay 603 as well as short circuiting the same in order to cause such relay to be energized. Release relay 603, upon deenergizing, at armature 616 opens the locking circuit of switching relay 610 thereby permitting the latter relay to release. At the resting contact of armature 616 release relay 603 closes an energizing circuit for release magnet 613. Release magnet 613 thereupon operates and releases the incoming selector repeater in the well known manner.

Having described the invention, its utility and operation, what is considered new and desired to have protected by Letters Patent will be set forth in the appended claims.

What is claimed is:

1. In a telephone system, a line, means including a selector and a connector for completing a connection to said line, means including a trunk line, another selector, and another connector in serial relation for extending another connection to said line, means for preventing the second connector from completing a connection with said line in case said line is busy in said first mentioned connection, means in said second selector controlled over the two talking conductors of said trunk line for causing said second connector to complete the connection to said busy line, means in said second selector for ap-

- plying a ground potential to the two talking conductors of said busy line, and means in said first selector controlled over the two talking conductors of the first connection responsive to the application of said ground potentials to said line conductors for initiating and completing the release of the selector and connector in the said first connection.
2. In a telephone system, a line, a non-numerical hunting switch, a plurality of numerical switches, means for successively operating said switches to extend a connection from said line, means for applying a characteristic potential to each of the talking conductors of said line, and means in said first numerical switch responsive to said application for releasing said numerical switches while said hunting switch is maintained operated.
3. In a telephone system, a line, a non-numerical hunting switch, a plurality of numerical switches, means for successively operating said switches to extend a connection from said line, means for applying a characteristic potential to each of the talking conductors of said line, a meter for said line, means in said first numerical switch normally effective to operate said meter before releasing, and means in said first numerical switch responsive to said application for preventing the operation of said meter.
4. In a telephone system, a switch train including a selector repeater, intermediate selectors, and a connector, means in said selector repeater for repeating impulses over an impulsive circuit to the intermediate selectors and connector to control their operation in establishing a connection to a called line, said impulsive circuit including a source of current and a battery feed relay in said selector repeater and successive bridges or loops through the line relays of the intermediate selectors and connector, said battery feed relay being energized over said impulsive circuit, and a local circuit in said selector repeater for maintaining said battery feed relay in energized position when the impulsive circuit is opened at the selector repeater during the impulsive period.
5. In a telephone system, a toll switch train including a two conductor trunk line, a transmission selector repeater, an intermediate selector, and a connector in serial relation, means responsive to impulses sent over said trunk line for operating said selectors and connector to extend a connection to a called line, two different sources of busy current at said transmission selector, and means in said transmission selector repeater operative responsive to the connector connecting with a busy called line for connecting one or the other of said sources to said trunk line dependent upon whether the called line is busy in a local or a toll connection.
6. In a numerical switch for use in telephone systems, means for directively operating said switch to select a group of trunk lines, a rotary magnet, a switching relay, a circuit closed after the directive movement of said switch for causing said magnet to operate said switch in search of an idle one of said trunk lines, contacts on said magnet for interrupting said circuit, contacts on said relay included in said circuit, means for operating said relay responsive to potential encountered on an idle trunk line to operate said relay contacts to open said circuit, and a locking circuit for said relay including the winding of said magnet, the magnet contacts, and said relay contacts.
7. In a telephone system, a switch, a plurality of trunk lines terminating in the bank contacts of said switch, said switch having a directive movement and an automatic hunting movement to select an idle one of said trunk lines, a test wiper and a release trunk conductor in said switch, a test bank contact for each of said trunk lines normally connected to a battery potential, means for grounding the test contacts of busy trunk lines, means for seizing and operating said switch in its directive movement and for grounding said release trunk conductor, a rotary magnet for operating said switch in its hunting movement, a switching relay in said switch, a circuit closed after the directive movement for operating said magnet, said circuit including said grounded conductor and contacts on said magnet and said relay, an energizing circuit for said relay including said grounded conductor, a winding on said relay, said test wiper, and only test contacts of idle trunk lines having battery potential thereon, and a holding circuit for said relay including said grounded conductor, another winding on said relay, said contacts on said relay and said magnet, and the winding of said magnet.
8. In a telephone system, a group of trunk lines, a switch having a directive movement and an automatic hunting movement to select an idle one of said trunk lines, a test wiper in said switch, a test contact for each of said trunk lines normally connected to a battery potential and accessible to said wiper, means whereby the test contacts of busy trunk lines are designated by a ground potential thereon while the test contacts of the trunk lines which are out of order are designated with an absence of potential thereon, a rotary magnet for operating said switch in its hunting movement, a local self interrupting circuit for said magnet in said switch, a switching relay in said switch energized only responsive to said wiper engaging a test contact having battery potential thereon, and contacts on said relay for opening said magnet circuit and for closing a holding circuit for itself including said magnet.
9. In a telephone system, a switch having

a directive and an automatic hunting movement, two test wipers in said switch and contacts engaged thereby responsive to the directive movement of said switch, a test relay in said switch energized over a circuit including the first wiper, another test relay in said switch energized over a circuit closed by said first relay through the second test wiper to start the hunting movement, and 10 means for maintaining said second relay in energized position over a circuit including said first test wiper to continue the hunting movement as long as said first wiper encounters busy test contacts of busy lines.

15 10. In a telephone system, a switch having directive and automatic hunting movements, a line relay in said switch for controlling the directive movements, two test wipers in said switch and contacts engaged thereby responsive to the directive movement of said switch, a test relay in said switch energized over a circuit including the first test wiper, a second test relay in said switch energized over a circuit closed by said first test relay through 20 the second wiper, a magnet for operating said switch in its hunting movement, means controlled by said second test relay for energizing said line relay, means controlled by said line relay for energizing said magnet, means 25 controlled by said magnet for deenergizing said line relay, and means for maintaining said second test relay in energized position over a circuit including said first test wiper to continue the hunting movement as long as 30 said first wiper encounters busy test contacts of busy lines.

11. In a telephone system, a rotary connector switch, a group of lines accessible to said switch, each line having a regular and a 40 special test contact, a resistance and a battery having one pole connected to the first of said special contacts and the other pole connected to the last of said special contacts, a line relay in said switch for directly controlling the 45 operation of said switch to select any line of said group, means in said switch controlled from the test contacts of the selected line and effective to energize said line relay only in case the selected line is the first line of the 50 group, and means for operating said line relay as a stepping relay to cause said switch to automatically hunt for an idle line in said group.

12. In a telephone system, a rotary connector switch, a group of lines accessible to said switch, each line having a regular and a special test contact, a resistance and a battery having one pole connected to the first of said special contacts and the other pole connected to the last of said special contacts, a line relay in said switch for directly controlling the operation of said switch to select any line of said group, means in said switch controlled from the test contacts of the selected line and effective to energize said line

relay only in case the selected line is the first line of the group, means for operating said line relay as a stepping relay to cause said switch to automatically hunt for an idle line in said group, and means for preventing the operation of said line relay responsive to the switch encountering the last contact of said group in its hunting movement thereby stopping the hunting movement when the last line is reached regardless of whether the last 75 line is busy or idle.

13. In a telephone system, a toll trunk, a local trunk, a combination two motion toll and local connector operable over either of said trunks, a marginal relay in said connector, means for seizing said connector by way of either of said trunks and for closing a circuit through a winding of said relay responsive thereto, the flow of current in said circuit being in one direction when the connector is seized by way of the local trunk and in the opposite direction when the connector is seized by way of the toll trunk, a second circuit for said relay closed through a second winding thereon, means whereby said relay is energized only when the flow of current in the first circuit is in the proper direction to assist the second circuit, and means controlled by said relay for applying two different guarding potentials to the test contact of the called line dependent upon whether it is operated or not.

14. In a telephone system, a calling line and a called line, means including a selector repeater, intermediate selectors, and a connector for completing a connection between said lines, means for feeding talking battery to both lines from said selector repeater, means for extending a holding circuit from said selector repeater to hold the intermediate selectors and connector in operated position, means responsive to the calling subscriber replacing his receiver for releasing said selector repeater and intermediate selectors, and means controlled over the called line in case the called subscriber has not replaced his receiver for maintaining said connector in operated position and for making said connection busy.

15. In a telephone system, a connector switch, means for seizing said connector over two paths and for operating said connector to complete a connection to a called line, means in said connector responsive to such connection for automatically applying ringing current to the called line in case the connector is seized over one path, means in said connector for preventing the application of ringing current to said line in case the connector is seized over the other path, and means for connecting ringing current to said line by way of said connector from a source in a switch preceding said connector.

16. In a telephone system, a calling line, a called line, a train of automatic switches

for completing a connection from the calling to the called line, a meter for the calling line, a circuit for operating said meter prepared responsive to the called subscriber answering, a circuit for releasing the first numerical switch in said train opened responsive to the called subscriber answering, means in said switch operated responsive to the calling subscriber replacing his receiver for completing said metering circuit to cause the operation of said meter and for preparing said release circuit, and a relay in said switch initially energized responsive to the called subscriber answering and subsequently deenergized responsive to the calling subscriber replacing his receiver for controlling said circuits whereby the release of said switch takes place only after the meter has been operated.

17. In a telephone system, a calling line, a called line, a train of automatic switches for completing a connection from the calling to the called line, a meter for the calling line, a circuit for operating said meter prepared responsive to the called subscriber answering, a circuit for releasing the first numerical switch in said train opened responsive to the called subscriber answering, and means in said switch for opening said meter circuit and completing said release circuit only after the meter circuit has been closed for a predetermined time.

18. In a telephone system, a calling line, a called line, a train of automatic switches for completing a connection from the calling to the called line, a meter for the calling line, a circuit for operating said meter prepared responsive to the called subscriber answering, a circuit for releasing the first numerical switch in said train opened responsive to the called subscriber answering, means in said switch for opening said meter circuit and for completing said release circuit only after the meter circuit has been closed for a predetermined time, and means in said switch for preventing the calling subscriber from interfering with the metering operation in case the calling subscriber should initiate a new call.

19. In a telephone system, a calling line terminating in a local automatic exchange, a called line terminating in a distant automatic exchange, a train of automatic switches for completing a connection from the calling to the called line, an inter-exchange trunk line included in said connection between the first and second numerical switches in said switch train, a group of trunk meter relays individual to said trunk line, a meter for the calling line, a circuit for operating said meter prepared responsive to the called subscriber answering, means responsive to the calling subscriber replacing his receiver for operating said trunk meter relays, means in said first numerical switch operated responsive to the operation of said meter relays for operating said meter a plurality of times,

means controlled by said meter relays during operation for maintaining said first numerical switch in operated position, and means for releasing said first numerical switch only after the meter relays have performed their metering operation.

20. In a telephone system, a calling line terminating in a local automatic exchange, a called line terminating in a distant automatic exchange, a train of automatic switches for completing a connection from the calling to the called line, an inter-exchange trunk line included in said connection, trunk meter relays individual to said trunk line, a meter individual to the calling line, means normally effective responsive to the calling subscriber replacing his receiver for operating said meter relays to operate said meter a plurality of times, means controlled by an operator for completing a toll connection to said called line while the same is busy, means in the first numerical switch in said inter-exchange connection thereafter controlled by the operator over said inter-exchange trunk line for preparing said switch for release and for initiating the operation of said meter relays, means controlled by said meter relays for maintaining said switch operated and for releasing the remainder of the connection, means in said switch for preventing the operation of said meter when the meter relays are operated, and means for releasing said switch independent of control from the calling line.

21. In a telephone system, an impulse repeater, an incoming line, a trunk line, said repeater having two relay coils arranged to be energized over said lines, respectively, means responsive to a deenergization of the first coil when the incoming line is broken for breaking the trunk line, and additional means for energizing the coil of the trunk line in a local circuit while the said trunk line is thus broken.

22. In combination, two lines, two electromagnet coils connected in series with said lines respectively, means responsive to a deenergization of one coil when the corresponding line is broken for breaking the other line, and additional means for maintaining the coil associated with the said other line in an energized condition by connecting the said coil in a local circuit while the said other line is broken.

23. In a telephone system, a repeater, a line incoming to said repeater and a line outgoing from said repeater, a line relay in said repeater arranged to be energized over the incoming line, a holding relay arranged to be energized over the outgoing line, and contacts on said incoming line relay effective when the line relay is deenergized by a break in the incoming line to break the outgoing line and to place the said holding relay in a local energizing circuit.

24. In combination, a line, a relay coil arranged to be maintained energized over said line, a sending device, means for operating said sending device to open said line a desired number of times and to close a local holding circuit for said relay coil each time the line is opened.
25. In a telephone system, a trunk line over which automatic switching mechanism is operated to set up a telephone connection, a control relay having a winding energized over said trunk line, a repeater and means for operating it to open said line a desired number of times, said automatic switching mechanism being responsive to the openings in the line to set up a telephone connection, additional means in said repeater responsive each time the line is opened to place said relay winding in a local holding circuit, and means in said automatic switching mechanism effective after the connection is set up for opening the line to deenergize said control relay.
26. In a telephone system, an impulse repeater having front-bridge and back-bridge relays, means for seizing said repeater and for thereupon energizing the front-bridge relay, means responsive to the energization of the front-bridge relay for energizing the back-bridge relay, a switch-over relay and means for energizing it, a locking circuit for the said switch-over relay controlled by said back-bridge relay, means for maintaining said back-bridge relay energized while impulses are being repeated so as to maintain said locking circuit for said switch-over relay.
27. In a telephone system, an automatic switch arranged to be controlled over a calling line to set up a connection to a desired called line, and means in said switch controlled over either the conductors incoming from the called line or the conductors outgoing to the called line, responsive to an unbalanced current flow in the two sides of the line, for releasing the switch.
28. In a telephone system, a trunk line divided into two inductively coupled sections, a battery bridge across each section of the trunk line including the exchange battery, and a differential relay common to both bridges.
29. In a telephone system, a trunk line divided into two inductively coupled sections, a bridge across the talking conductors of the first section including the exchange battery, the windings of a double-wound differential relay, and an impedance device, and a bridge across the talking conductors of the other section including the exchange battery, the windings of the said differential relay, and another impedance device.
30. In a telephone system, a first selector repeater for use in a telephone system for setting up a connection from a calling line through other switching apparatus to a called line, a line relay in said first selector repeater through which talking current is supplied to the calling line during conversation, a back-bridge relay in the first selector repeater through which talking current is supplied to the called line, a differential relay in said first selector repeater, and circuit connections for supplying the current to the said line relay and to the said back-bridge relay through said differential relay.
31. In a telephone system, a first selector repeater for use in a telephone system for setting up a connection from a calling line through other switching apparatus to a called line, a line relay in said first selector repeater through which talking current is supplied to the calling line during conversation, a back-bridge relay in the first selector repeater through which talking current is supplied to the called line, a differential relay in said first selector repeater, and circuit connections for supplying the current to the said line relay and to the said back-bridge relay through said differential relay, and means responsive to an operation of said differential relay when the current flow is unbalanced in either the calling line or the called line for releasing the connection.
32. In combination, a relay group and a trunk line incoming thereto, said relay group including a line relay and a release relay, means for energizing the line relay over the trunk line, circuit connections controlled by the line relay for maintaining the release relay shunted until the line relay energizes, and means responsive to a subsequent deenergization of the line relay for bringing about a circuit change so that the said release relay is shunted when the line relay again energizes.
33. In a telephone system, a combination toll and local connector accessible to toll selectors and local selectors, a line relay in said combination connector included in a bridge across the talking conductors, a polarized discriminating relay connected in said bridge in series with the line relay, said local selectors being arranged so that the current flow through the bridge in the connector is in such a direction as not to operate the polarized relay when the connector is seized by a local selector, said toll selectors being arranged so that the current flow is in the proper direction to operate said polarized relay when the connector is seized by a toll selector, and contacts on said relay arranged to adapt said connector to operate as a toll connector.
34. In a telephone system, wherein a switch arranged to operate in either of two ways is accessible to two groups of preceding switches and has a line relay bridged across incoming talking conductors to enable it to respond to current flow over the line from a switch of either group, a polarized discriminating relay connected in circuit with said line relay, and

- circuit connections associated with the said preceding groups of switches such that the polarized relay is operated when the said automatic switch is seized by a preceding switch of one group and is not operated when said automatic switch is seized by a preceding switch of the other group. 5
35. In a telephone system wherein a switch arranged to operate in either of two ways is accessible to two groups of preceding switches and has a line relay bridged across incoming talking conductors to enable it to respond to current flow over the line from a switch of either group, a polarized discriminating relay connected in circuit with said line relay, circuit connections associated with the said preceding groups of switches such that the polarized relay is operated when the said automatic switch is seized by a preceding switch 10 of one group and is not operated when said automatic switch is seized by a preceding switch of the other group, and circuit connections controlled by the said polarized relay for causing the said switch to operate in 15 one way when the polarized relay is not operated, and to operate in another way when the polarized relay is operated. 20
36. In a combination connector arranged to operate in either of two ways, talking conductors incoming to said connector, a polarized relay connected in a bridge across said talking conductors, and connections controlled by said polarized relay for causing said connector to operate in either of the two ways 25 depending upon whether the polarized relay is operated or not. 30
37. In combination, a combined local and toll connector, talking conductors incoming to said connector over which connection is established thereto when the connector is to operate a local connector and also when it is to operate as a toll connector, a discriminating relay connected in a bridge across said talking conductors, and means for operating 40 said discriminating relay over the talking conductors subsequent to the seizure of the connector only in case the connector is to operate as a toll connector. 45
38. In combination, an automatic switch having a line relay, a second relay, and a third relay, said switch having also a primary operating magnet, a secondary operating magnet, and a release magnet, said line relay being arranged to operate over the incoming line of the switch when it is seized, circuit connections for operating the second relay responsive to the operation of the line relay, contacts on the second relay for opening a point in the circuit of the release magnet 50 and for closing a point in the operating circuit of the primary and secondary magnets, means effective to energize the third relay after the line relay is controlled over the incoming line to operate the primary magnet, 55 contacts on the third relay for closing a multiple point in the said operating circuit and for opening a further point in the circuit of the release magnet, and other contacts on the said third relay for disconnecting the operating circuit from the primary magnet and for connecting it to the secondary magnet. 70
39. In combination, an automatic switch having a line relay, a second relay, and a third relay, said switch having also a primary operating magnet, a secondary operating magnet, and a release magnet, said line relay being arranged to operate over the incoming line of the switch when it is seized, circuit connections for operating the second relay responsive to the operation of the line relay, contacts on the second relay for opening a point in the circuit of the release magnet 75 and for closing a point in the operating circuit of the primary and secondary magnets, means effective to energize the third relay after the line relay is controlled over the incoming line to operate the primary magnet, contacts on the third relay for closing a multiple point in the said operating circuit and for opening a further point in the circuit of the release magnet, other contacts on the said third relay for disconnecting the operating circuit from the primary magnet and for connecting it to the secondary magnet. 80
40. In combination, an automatic switch having two incoming talking conductors, subscribers' lines accessible to said switch and each having two talking conductors and a test conductor, said switch having wipers through which connections are made to the conductors of subscribers' lines, one of said wipers being a test wiper and two of said wipers being talking wipers, the said talking wipers being normally disconnected from the incoming talking conductors, a switching relay arranged to energize when the connector is set on an idle line, and means effective 90 when connector is set on a busy line for connecting said switching relay to one of the incoming talking conductors and for connecting the test wiper of the switch to the other incoming talking conductor. 100
41. In a telephone system, a connector switch having access to subscribers' lines, means for operating said connector into association with a line and for testing the line for a busy or idle condition thereon, talking conductors incoming to the switch, a switching relay arranged to connect the incoming talking conductors through the wipers of the switch to the called line in case the called line is found to be idle, and means effective in case the called line is found to be busy for connecting said switching relay to one of the incoming talking conductors. 105
42. In a telephone system wherein connections are set up to a called line through a 110
- 115
- 120
- 125
- 130

transmission selector and a connector, a switching relay in said connector operable to complete the connection to a called line after the connector has been set, and a circuit for energizing said relay extending from said transmission selector to said connector over a talking conductor.

In witness whereof, I hereunto subscribe my name this 4th day of August, A. D. 1928.

10
